MINE AND OTHER CAR

Audley Hart Stow, deceased, late of Charleston, W. Va., by Sanford Investment Company, Wilmington, Del., a corporation of Delaware, assignee

Original No. 1,961,017, dated May 29, 1934, Serial No. 424,132, November 15, 1920. Application for reissue May 28, 1936, Serial No. 32,381

117 Claims. (Cl. 105—364)

This invention relates to improvements in mine and similar rail cars.

The objects of this invention are to produce such a car in a form adapted to meet conditions and to function as hereinafter described, including adaptation to carry the largest load possible in given "out to out" dimensions prescribed by conditions in the mines—the width and height in passages through which extend the rail tracks to be traversed by the cars. Lading capacity depends on location of the mine car bottom or floor relative to the track rails and also on the thickness (or thinness) of the floor and also the length of the car and the form of body walls or upper structure rising from the floor. Increasing the lading capacity of the car by lowering the floor or bottom is a feature of this improvement. Increasing the length of said cars from former practice requires changes in structure in order to give the car stability or rigidity. In this connection, it is to be noted that in these cars a short "wheel base" is desirable, in order that the car may readily pass such short track curves as are ordinarily present in and at coal mines. The short wheel base is produced by placing the axles near each other, in order that the wheels at each side of the car will be near each other.

When a car is made longer and the axles are placed to produce such a short wheel base, each end of the car will extend outward beyond the adjacent axles, and the structure of the car must be such as to keep those ends from sagging or bending downward during operation of the car.

Building the car to carry a load extending closer to the rails and having greater length, calls for revising the structure of cars heretofore in use, to afford the required strength and durability. That variation for more capacity requires changes in organization, an important feature of which is placing the car floor or bottom low relative to the car axles, whereby the floor is placed as near to the track rails as is permissible.

A further object of the invention is to produce a car having a horizontal traction truck frame which is strong relative to the lading-retaining walls rising from the truck, in order that the truck may receive tension and compression strains during the operation of the car, while the lading retaining walls have merely enough strength or stability to ordinarily retain normal position but yield to abnormal strains tending to deform said walls and so avoid or limit transmission of strains to the track under wreck conditions.

In mining practice, there are mine car wrecks

similar to railroad wrecks, and there are also a large number of wrecks resulting from roof falls in the mines. In either kind of wreck, it is desirable to limit the damage done to the cars. The damage or loss is greater when the traction truck is destroyed. Then the removal of the wrecked car and the repair of the car lead to more delay and expense. In cars in which the side walls are arranged to take haulage strains those walls are so strong as to tend to transmit ordinary wreck strains or roof fall strains to the truck, whereby the truck is broken or bent along with the wrecking of the side walls. Thus the car is difficult to remove from the mine and has almost no scrap value when so removed. In this improved car, it is preferred to avoid so constructing the car as to depend upon the side walls for taking haulage strains.

It is preferred to concentrate in the traction truck all the metal necessary to take care of the haulage strains, both tensile and compressive. And all the metal is so placed in the car as to give the maximum strength per pound of metal. There is thus needed only a relatively light and flimsy lading-holding upper body or structure which may be crushed by a fall of the roof and be readily removed from the traction truck with relatively trifling loss. If the fall of the roof occurs on one of these loaded cars, the car lading will more usually so cushion the fall of the roof that the traction truck will seldom be seriously damaged. When these improved cars are telescoped, the ends of the trucks will seldom hit so squarely as to prevent the trucks from sliding either under or over each other and so avoid serious damage to the trucks.

Some mine cars are constructed to discharge their lading by gravity, without tilting the car. Mine cars having displaceable bottom doors are of that kind. Other cars are tilttable for discharge of the lading by gravity. Of those there are some in which only a part of the car is tilted for discharging the lading. The invention relates to such cars as are tilted bodily—the entire car, including the truck, being tilted—either endwise or sidewise, for discharging the lading by gravity. The drawings illustrate an end-dump car constructed for such bodily tilting.

In mine operation, it is desirable to have the wheels free for rotation on the axles, in order that, on track curves, the wheels may freely turn independently of each other, the axles being at the same time free for slow or creeping rotation in axle bearings which are supported by the side beams or side sills, that slow turning being caused

by slight frictional engagement between the wheels and axles. The purpose of that slow rotation of the axle is to avoid wearing by the wheels on only one part of the axle journals, as is the case when the axles do not turn.

Because, when, in the improved car the car axles are continuous from journal to journal, the floor is placed below the axles, whereby the axles are in the lading holding body, it is desirable to prevent the lading from making engagement with the axles in such manner as to interfere with the slow rotation of the axles. If the car is an end-dump car, it is also desirable to associate with the axles means for guiding the lading over the axles, without contact with the axles, when the car is tilted into the end-dumping position. Accordingly the improved car preferably includes axle deflectors and axle hoods and axle tubes which shield the axles from contact with the lading. If the car is an end-dump car, as herein described, deflector plates placed over the axles and having sloping faces at the rear of the axles serve to guide the lading over the axles when the car is in the end-dump position; and when the car is in the horizontal position, those deflector plates keep the lading from lying on the axles and preventing rotation of the axles. If the car is to be turned sidewise for discharging its load, the sloping face of the deflector is not needed; but a hooding form cover may be placed over the axles to keep the lading from bearing upon the axles. In either form, these axle covers are to be made strong enough to avoid bending when large and heavy pieces of lading fall upon the covers. It is also to be noted that contact of lading with rotating axles is to be avoided, because such contact would grind the lading.

In the accompanying drawings:—

Fig. 1 is a bottom view of a traction truck constructed in accordance with the invention, the outer ends of the axles being broken away;

Fig. 2 is a partial sectional side elevation of the improved mine car, showing the lading holding body in its working position with relation to the improved traction truck, the rear end of the car being shown in longitudinal vertical section on the line, 2—2, of Fig. 1, certain parts being shown by dotted lines;

Fig. 3 is a vertical cross section on the line, 3—3, of Fig. 1;

Fig. 4 is a horizontal section taken on the line, 4—4, of Fig. 5;

Fig. 5 is a vertical section on the longitudinal middle line, 5—5, of Fig. 4;

Fig. 6 is an outer side view of a portion of the longitudinal side sill of the improved traction truck, showing the axle boxing in position;

Fig. 7 is a detail section on the line, 2—2, of Fig. 1, exposing an inside view of a portion of the said longitudinal side sill;

Fig. 8 is a vertical cross-section on the line, 8—8, of Fig. 6;

Fig. 9 is a detail, upright, longitudinal section showing another form of the bottom pivoted spring draw-bar;

Fig. 10 is a detail upright cross-section on the line, 10—10, of Fig. 1;

Fig. 11 is a detail, upright, cross-section on the line, 11—11, of Fig. 9;

Fig. 12 is a detail elevation of the end ship channel shown in Fig. 4;

Fig. 13 is a detail section of still another form of pivoted spring draw-bar;

Fig. 14 is an upright longitudinal section of a

form of rigid draw-bar, as applied to the front of the car;

Fig. 15 is a detail upright cross-section of a reinforced belt or binder;

Fig. 16 is a detail section showing another form 5 of reinforced belt or binder;

Fig. 17 is a detail section showing still another form of reinforced belt or binder;

Fig. 17A is a view similar to Fig. 17;

Fig. 18 is a detail upright longitudinal section 10 showing a swinging draw-bar;

Fig. 19 is a detail section, on the line, 19—19, of Fig. 18;

Fig. 20 is a detail vertical cross section on the line, 20—20, of Fig. 2, showing a somewhat different style of axle boxing, from that shown in Figs. 6, 7, and 8;

Fig. 21 is a detail cross section of another form of axle boxing;

Fig. 22 is a detail vertical cross section on the line, 22—22, of Fig. 6 of still another form of axle boxing;

Fig. 23 is a detail section of still another form of axle boxing;

Fig. 24 is a detail vertical longitudinal section 25 on the line, 24—24, of Fig. 25, showing an inside view of the swinging axle boxing which forms a portion of the spring wheel truck;

Fig. 25 is an upright cross-section through the center of the axle on the line, 25—25, of Fig. 24;

Fig. 26 is a detail vertical section on the line, 26—26, of Fig. 24;

Fig. 27 is a view similar to Fig. 4, showing solid end bumpers and a center draw-bar located between the upper and lower flanges of the end channel;

Fig. 28 is a detail longitudinal section on the line, 28—28, of Fig. 27;

Fig. 29 is a view similar to Fig. 28 of a still 40 different style of bottom pivoted spring draw-bar;

Fig. 30 is a side view, on a smaller scale, of substantially the same portion of the longitudinal supporting side sill shown in Fig. 24;

Fig. 31 is a view similar to Fig. 29, showing a 45 still different style of draw-bar;

Fig. 32 is a similar upright cross-section to that along the line, 32—32, of Fig. 24, showing, however, a different form of spring wheel truck;

Fig. 33 is a broken outside view of the rear end of the traction-truck, showing the arrangement 50 of the wheel brake fulcrum rod;

Fig. 34 is a view similar to Fig. 5 of the preferred spring draw-bar;

Fig. 35 is a front view of the draw-bar half 55 round filler and its base plate, which form the pivot of the center pivoted draw-bar;

Fig. 36 is a detail, outside elevation of the swinging or drop axle boxing shown in section in Fig. 32;

Fig. 37 is a cross section through a narrow gauge traction truck between the center car belt and the car wheel hoods, showing more particularly outside longitudinal supporting side sills, together with one method of supporting 65 the car bottom and axle hoods;

Fig. 38 shows one form of an automatic car-coupling device riveted to the end channel.

In all longitudinal views, the left hand end is considered the front end and the right hand end 70 the rear end of the car.

The first part of the description will relate to combining parts to form a complete car, reference being mainly to Figs. 1 to 8, inclusive, and this part of the description being under main 75

heads, as follows: (A) traction truck; (B) floor structure; (C) end structures; and (D) upper structure.

The traction truck comprises (a) longitudinal side beams or side sills, (b) end sills or end beams, (c) corner fastenings joining the side beams to the end beams, (d) wheels and axles, and (e) axle boxings supported by the side beams.

10 The floor occupies the space enclosed by the side beams and the end beams and makes connections with the side beams and end beams, as will be explained further on.

15 The end structures are composed of the end beams and auxiliary bumper and coupler elements, as will be described further on.

20 The upper structure comprises the lading retaining walls extending upward from the side beams and the end beams. In the form of car 25 shown (an end dump car), the end door is a part of the upper structure.

25 The description of the complete car will be followed by a description of other forms of various parts of the car, such other forms being illustrated by Figs. 9 to 38, inclusive.

The traction truck

The longitudinal side sills consist, preferably, 30 of common stock metal I-beams, 1 (Figs. 1, 2, 3, etc.); the rigid backing for the bumper being, preferably, metal ship-channels, 2. With the draw-bar, 30—11, 30—12, over the bumper as in Figs. 2 and 5, the maximum tensile haulage strain necessarily comes in line with the upper 35 flange of said ship channel, which, for heavy service, is preferably reinforced by the metal channel reinforcing strap, 3, of approximately the width and length of the upper flange of said ship channel, to which it is suitably riveted. On 40 the upper faces of the upper flanges of both I-beams, at both ends of the car, are preferably riveted to the corner connecting plates or bars, 4 (Fig. 4), which extend past the ends of the I-beams so as to rest flush on top of the ends of the 45 upper flanges of the ship channels and under the ends of the said reinforcing straps, raised sufficiently for that purpose. The king rivets, 5, (Fig. 4) are then passed through the raised ends of the channel reinforcing straps, 3, 50 through the projecting ends of the corner connecting bars, 4, and through the upper flanges of the said ship channels, 2. The tensile haulage strains delivered by the draw-bar against the upper flanges of the ship channels and the attached channel reinforcing straps, 3, will therefore 55 subject the said king rivets to double shear.

Within the rectangular frame formed by the side beams and the end channels, in each corner of said frame, is an upright angle connection, 6, 60 having one flange bearing against the inner face of the web of the adjacent side beam and having its other flange bearing against the inner or back face of the end channel member, 2, the flanges of said angle connections being riveted 65 to the members against which they rest.

Thus the side beams, 1, and the transverse ship channels, 2, are joined to one another. Additional means will be described which serve to further strengthen the connection between the 70 side beams and the ship channel.

Although the term, "ship channel" is employed, to indicate a preference, it is to be understood that by this term is meant such a channel as is shown in the drawings, with ample flanges 75 having parallel inner horizontal wall surfaces

that will support the bumper element, 15, and permit it to compress in absorbing impact shock, without the pinching that would occur if the flange walls were tapered at their inner surfaces. The end channel, 2, is shown in Figs. 2, 5, 9, 13, 14, 18, 28, 29, 31, 34, and 38, to have the flanges and also the web plates of such proper form.

If the bumper channel, 15 (Fig. 5) for example, fits snugly within the end channel, 2, as shown, obviously, the bumper channel may be more readily inserted within the end channel, if the inner free edges of the flanges (those facing each other) are rounded, as shown, instead of being square. On the other hand, the 15 end channel will, obviously, be stronger, if the outer corners, where the flanges and web plates meet, are square, as shown, instead of rounded.

For the smaller cars used in thin vein coal mining, a metal six inch I-beam is about the right size, and as it happens, just about gives a bumper which closely matches the height of the old all-wood bumper and yet gets the bottom of the bumper down to within say three and one half inches of the top of the rail, which is as close as is otherwise practicable. In the same way, for the heavier cars of this type, the eight inch I-beam is the right size, which also makes the top of the bumper fit the top of the old all-wood bumper of this size car, while still putting 30 this car bottom down within say four inches of the top of the rail.

While the longitudinal side sills of this traction-truck may be constructed from other forms of structural steel or may be composed of sectional built-up or composite beams, it is preferred to use the common stock I-beams, as shown in the several drawings, and which are admirably adapted for the purpose.

The axles and wheels

40

The frame composed of the side beams and the end members is supported by the two car axles, 66. The axles extend through the side beams or sills, 1, 1, so that each axle is above a part of the 45 beams and below a part of the beams (Figs. 1, 2, 3, 23, 24, and 32). As described further on, the axles pass through axle boxings applied to the side beams or sills in alignment with openings in the side sills. Said axle boxings are also shown 50 extending through openings in the side sills, as will be described further on.

On each axle are two wheels, 66—A. In Figs. 1, 2, 3, and 32, the axles extend outward through the side beams and axle boxings and receive the 55 wheels at the outer sides of the side sills.

The axles are placed at opposite sides of and equidistant from the upright, transverse, middle plane of the car, the distances of the axles from that plane being so short as to leave a considerable part of each end of the car projecting beyond the axles, whereby the car is supported in three parts, one part being between the axles, another part being forward of the front axle, and another part 60 being rearward of the rear axle. This arrangement places the wheels near each other relative to the length of the car and gives the car a "short wheel base". To that feature, reference is again made further on.

70 The axle boxings are next described.

Axle boxings

For the first form of axle boxings, reference is made to Figs. 1, 2, 3, 6, 7, and 8..

75

Owing to the severe strain on the axle boxings, when the wheels hit the horns in the tipple structure during the end-dumping operation, there is a tendency to shear off the axle boxing rivets, 5 if the axle boxings are cast in halves and merely riveted flatwise to the upright webs of the I-beams. The rivet holes are necessarily somewhat larger than the rivets, in order that the rivets may be readily and quickly inserted, while hot. Necessarily therefore, when the rivets are cool there is 10 a certain amount of play, which permits the starting of shearing action of the axle boxing on the rivets. This may be remedied by the improved removable interlocking axle boxing shown in Figs. 15 6, 7, and 8. In those drawings the axle boxing consists of the axle bearing proper, 60, (Figs. 6 and 8) at right angles to and in the center of a face plate, 60-1, parallel to and fitting against the outer face of the vertical web of the I-beam. 20 1. Two horizontal angular webs, 60-2, one on either side of the axle bearing proper serve to reinforce the bearing. The face plate, as shown, extends down from the upper flange of the I-beam, 1, to the lower flange of the said I-beam; 25 the said face plate, and the adjacent vertical web of the I-beam being perforated to receive a suitable number of rivets, 64, 65, to hold the axle boxing in place during service.

The axle bearing proper has a cylindrical inward extension, 60-3, which just neatly fits the 30 hole in the web of the I-beam prepared to receive it, and which therefore may be termed the axle interlocking extension. (Figs. 7 and 8.) Fig. 7 shows the inner face of the I-beam. With this arrangement, therefore, the axle boxing interlocks directly with the web of the I-beam, and may 35 be machined so as to secure what is termed, in bridge practice, the full pin value of the said inward extension, 60-3, of the axle bearing 40 proper.

The axle bearing proper, 60, (Fig. 8) has preferably a broad wheel bearing or outside vertical face, as shown, the axle bearing proper being conical from said wheel bearing toward the face plate, 60-1, (Fig. 6) so as to give as broad a 45 base as practicable, where the axle bearing proper merges into said face plate, the several parts of the axle boxing herein described being cast in one piece.

For the heaviest service, cast steel boxings are 50 preferable, but for medium or light service properly designed cast iron boxings are sufficient. For rigid cast steel axle boxings rivets are preferable. The cooling strains incident to riveting may, 55 however, result in the fracture of cast iron axle boxings, so that, with cast iron boxings, bolts and lock-nuts are preferable. Cast iron axle boxings should be readily removable as shown, in case of breakage. If made of cast iron secured by 60 bolts and lock-nuts, the axle boxing, if broken or worn out, may be removed and replaced by a new one.

There may be a reinforcing plate, 61, (Figs. 7 and 8) on the inner side of the I-beam, and in a 65 position corresponding to the axle boxing face plate, 60-1, (see dotted lines, 61, Fig. 6), the cylindrical inward extension, 60-3, of the axle bearing proper also extending through said reinforcing plate (see Fig. 8). The reinforcing plate, 70 61, will tend to compensate for the metal removed to permit the insertion of the axle, 66, and axle boxing rivets, and will, in addition, give a double shear value to the rivets. The inner reinforcing plate, 61, may, however, be entirely omitted (see Fig. 21).

An oiling duct, 67, (Fig. 6) may be conveniently placed in the axle bearing proper, just above the angular web, 60-2, and slanting downward, as shown. In practice, however, it is usually found that sufficient oil leaks in from the adjacent loose 5 wheels to answer the purpose of lubricating the axle boxing. In this connection it is to be remembered that, preferably, the axles are to be given only a slow turning in these bearings.

Axle tubes

10

A tube surrounding the axle is of advantage in several ways. If the tube, 100, (Fig. 20) is connected with what may be termed the inner axle bearing, 62, by means of the pipe coupling, 101, 15 the I-beams will be rigidly held in place under the compressive haulage strains. In addition to such bracing action by the axle tube, it may prevent downward denting of the crown of the 20 axle deflector, 9-2, by rock or large lumps of coal falling on said crown. Thus the axle tube serves to brace the side beams and to protect the axle.

Car floor or bottom

25

The car floor or bottom is preferably formed of horizontal metal plates and axle covers or deflectors and bumper end structure deflectors. The horizontal plates are the approximately rectangular metal plates, 1-1, 7-2 and 7-3 (Fig. 30 1, etc.) also herein termed spaced-apart lading bottom portions.

The end edges of the plates are shown bearing 35 against the lower parts of the I-beams and riveted to said parts of said beams, and the plate, 7-3, underlapping the lower flange of the rear end channel, 2, and being riveted to said flange. The forward corners of the traction truck are further reinforced on the under side by the metal corner bottom plates, 8, the space between 40 the bottom sheet, 7-1, and the front bumper being filled by the metal bumper deflector plate, 9-1; the metal front axle deflector plate, 9-2, filling 45 the space between the forward bottom plate, 7-1, and the middle bottom plate, 7-2; the metal rear axle deflector plate, 9-3, filling the space between the middle bottom plate, 7-1, 50 and the rear bottom plate, 7-3; the several parts of the traction-truck being riveted or otherwise suitably attached together. It is to be noted that the spaced-apart lading bottom portions, 7-1, 7-2, 7-3 (Fig. 1) are approximately 55 horizontal, whereas the bumper deflector plate, 9-1, and the axle deflector plates, 9-2, 9-3, also serve as lading bottom or floor portions, but may, obviously, also be termed, for the purpose 55 of distinction, lading bottom or floor portions which are inclined longitudinally of the car.

Where the service is unusually severe, the traction-truck will be somewhat stronger, if it is 60 completely sheeted over on the under side from end to end with plates like the plates, 7-1, 7-2, 7-3, or such a single plate, the deflector plates in such construction serving mainly as deflector plates. But substantial economy in material 65 will be gained by so designing the deflector plates that they will also serve as parts of the traction truck bottom or floor, where the service for which the particular car is designed, permits.

With cradle dump mine cars, the traction-truck is also preferably sheeted over at the under side from end to end, the deflector plates proper being omitted, and other members being substituted, as described further on.

70

75

75

Deflector plates

There are two main varieties of deflector plates: (first) the forward or bumper deflector plate, and (second) two axle deflector plates, both of which latter are preferably of exactly the same dimensions and construction for the sake of economy in shop work.

The forward or bumper deflector plate, 9-1 (Fig. 1, etc.), is inclined at such an angle with the horizontal, say twenty degrees when the car is level, that the said bumper deflector plate will be sufficiently inclined forward when the car is in the end-dumping position, usually forty five degrees, that the car standing on the forty five degree pitch will, with certainty under adverse conditions, start the coal that is on the bumper deflector plate. Therefore a twenty degree bumper deflector plate, when in the dumping position will have a pitch of twenty five degrees, ample for the purpose indicated. Coal, once started on a twenty five degree pitch, will not of itself come to rest on that pitch, which, for coal on sheet iron, is very nearly the angle of repose.

The lower, rear edge of the bumper deflector plate, 9-1 (see Fig. 5), is preferably riveted to the upper forward face of the forward bottom plate, 7-1; and the forward upper end of the said deflector plate is extended over the channel reinforcing strap, 3 (see also Fig. 4), and suitably riveted, together with the said channel reinforcing strap, to the upper flange of the front end channel, 2.

The lower, rear edges of the two axle deflector plates, 9-2 and 9-3, are also, preferably, riveted to the upper, forward faces of the corresponding bottom plates, 7-2 and 7-3, this being similar to the attachment of the bumper deflector plate, 9-1, last above described.

The axle deflector plates, as shown, are to be regarded as deflector plates proper, and they may also be termed axle hoods. In order to avoid the lading binding against the axle, and thus preventing the axle from rotating in its bearings, each deflector plate proper is preferably extended up over its axle and back down partially around the axle to a vertical position from which it is extended downward to meet the adjacent bottom plate, and then bent forward at right angles (see 10-1, Fig. 7) so as to rest on the bottom plate to which it is suitably attached, as by riveting.

Thus the axle deflector plates usually consist of two structural features or parts, to wit: the sloping or inclined axle deflector plates proper, 9-2 (Fig. 7), and the axle hoods, 10-1, which two parts may of course be made separately and suitably united.

Axle hoods

In the case of cars dumping sidewise, sloping deflector plates, properly speaking, will not be required. The axle hoods will, however, be required to keep the lading from so binding the axles as to prevent their turning.

Axle hoods, properly speaking, preferably consist of an inverted U-shape trough (see dotted lines 10-2, Fig. 6). The complete axle hood required or suited for sidewise dumping cars is preferably supported and reinforced in the same manner as above explained regarding the axle deflector plates.

Crown reinforcing

Where the car is to receive large pieces of rock, (in the absence of the axle tubes, 108, above

described (Fig. 20)) the crown of the axle deflector plates may be so dented as to bear on the axle underneath and prevent the axle from turning. To avoid such denting, each plate may be reinforced, as by a long concave metal strip, 136, (Fig. 24) parallel to and resting on said crown, and riveted thereto, and extending over at least a material part of the length of the crown. This reinforcing plate may be placed against the under face instead of on the upper face of said crown.

The I-beams, 1, as already stated, must be held rigidly in line, under compressive haulage strains to insure the development of their full strength. This may be accomplished in a number of ways. For example, the lower bend of the forward part of the deflector plate, 9-2, (Fig. 7) in combination with the rear edge of the center bottom plate, 7-2, riveted to the lower flange of the I-beam, 1, and said lower bend being riveted to the plate, 7-2, make a most efficient angular cross brace, sufficient to insure the maximum strength of the I-beam in so far as its lower flange is concerned. It, therefore, is only necessary to insure the correct alignment of the upper flange of the said I-beam. That may be done in several ways.

As shown in Figs. 7 and 10, the angle plate, 137, (also dotted lines, 137, Fig. 3) is riveted to the vertical (forward) face of the axle deflector plate, 9-2. The other leg of the said angle plate is placed in position against the inside reinforcing plate, 61, and riveted by the same rivets, 64, as are used for the inside reinforcing plate, 61, thus holding the web of the said I-beam in the desired position, and causing the alignment of the upper flange of the I-beam.

The same result may be obtained simply by means of the I-beam or side sill bridle, 138, (Fig. 10 and Fig. 32) consisting of the main upper bridle, 138, and the lower bridle, 138-1. The upper bridle has one end turned over and down and back under the upper, outer I-beam flange edge, suitably fitted to securely engage the edge of said flange. From this point, the said upper bridle passes over the said upper flange, resting on the same, until the inner edge of said flange is reached, at which point it is turned down sharply, at say an angle of forty-five degrees to the horizontal, till it meets the crown of the axle deflector plate, at which point it is again bent horizontally. It is then also bent transversely, so as to conform to the curved crown or upper face of the said axle deflector plate, to which it is securely riveted. Evidently the upper I-beam or side sill bridle, 138, may be extended clear across the crown of the said angle deflector plate to form the axle deflector plate brace, 136 (Fig. 24) previously described.

The lower part, 138-1, of the I-beam bridle, 138, (Fig. 10) is shown as abutting against the upper edge of the reinforcing plate, 61, from which point it is extended horizontally until it meets the under sloping face of the upper part of the bridle, at which point it is bent downward to conform to the slope of the said upper part, to which it is then securely riveted.

The said lower part of the bridle is not particularly essential, as the sharp bend in the upper part, at the upper, inner I-beam flange edge will evidently keep the upper part of the I-beam from creeling or turning inward. In cases where the inside reinforcing plate, 136, is not used, the outer edge of the lower part of the bridle, if used, will of course be extended still further outward

so as to bear against the vertical web of the I-beam.

The axle deflector plates may also be attached to the web of the I-beam by an angle connection, 5 139, (Fig. 24) riveted to the deflector plate and to the I-beam web.

A wood plank bottom in a traction-truck of this type usually necessitates a certain amount of added cross bracing, necessarily of metal to 10 insure the alignment of the side sills under stress. The labor construction costs on small cross bracing is a relatively large item. Thick sheet metal 15 flooring extended over the under side of the truck and secured to the side sills, will serve as a reinforcing and cross-bracing bottom, will reduce the labor costs on the cross bracing, will make a 20 stronger truck, and will give the car an increased capacity, and has the further advantage, where the lading is wet slack, as often enough happens, 25 of more readily and completely emptying the car of its lading than is done with a wood bottom.

The wood bottom may be made slightly cheaper than the sheet metal bottom, but the wood bottom can not well be made less than say one and 25 one half inches thick, the bottom plank resting on the upper faces of the inner lower I-beam flanges, say one-half inch thick. By riveting say one-quarter inch sheet iron on the lower side of the bottom flanges, there is gained a depth of say 30 two inches lading capacity, which of itself will more than offset any slight difference in cost that may be in favor of the wood-bottom truck.

Axle deflector supports

35 As means for supporting or reinforcing the axle deflector plates, reference has already been made to the bridles, 138, (Fig. 10) and to the member, 136, resting lengthwise on the crown of the axle deflector (Fig. 24). The ends of the crown or 40 upper part of the axle deflectors, may also conveniently be supported by the inner ends of the axle boxings or bearings, 68-3 (Figs. 2, 3, 7, and 8).

End structures

45 The main features of the end structures, comprising the channel, 2, and associated members, present in the car of Figs. 1 and 2, will now be described by reference to Figs. 1, 2, 4, and 5.

The simplest and most inexpensive form of 50 spring bumper probably comprises several approximately parallel wood springs, flat wood strips, 11-1, 11-2, 11-3, and 11-4, on edge, i. e. with their greatest transverse dimension parallel to the vertical web of the end channel, 2. 55 The ends of the wood spring, 11-1, next the said channel web rest against wood blocks, 12-1, (Fig. 4), and between it and the vertical channel web. In the same way, the ends of the wood 60 springs, 11-2 and 11-3, rest on the wood blocks, 12-2, and 12-3, respectively, similarly placed. No wood block is however provided for the wood spring, 11-4, as its ends should come to a bearing against the next inner wood spring, 11-3, before the thrust against the center of the bumper 65 forces the center of the inner spring, 11-1, against the adjacent vertical face of the channel web.

To hold the four wood springs in place against 70 the end channel, four bumper bolts also herein termed bumper holding bolts, are provided, the two center bumper bolts being, 13-1, and the two end bumper bolts being, 13-2, (Fig. 4). The four bumper bolts are placed in the vertical centers 75 of the four wood springs and the end chan-

nel. The two center bumper bolts are at right angles to the end channel and to the wood springs. The two end bumper bolts are approximately at right angles to the curved face of the bumper, and thus at an oblique angle with the 5 channel and the angle member, 6, and the two angle bumper bolt blocks, 613, resting in the angles, 6, and having their outside faces parallel to the inner faces of the bumper bolt nuts, 614, thus giving said bumper bolt nuts a full even 10 bearing. The two center bumper bolts are placed as close together as otherwise practicable, the two end bumper bolts being as far apart as practicable for the purpose indicated.

The wood springs are preferably shaped to 15 form, when assembled, such longitudinally curved surface as may be desired for the service (see Fig. 4). In order to protect the outer vertical faces of the assembled wood springs, as well as in part to retain the wood springs in place, the metal 20 bumper face strap, 14, (of a width approximately equal to the depth of the wood springs) is placed on the front face of the assembled wood springs, and curved to fit said front face, (see Fig. 4).

The bumper center plate, 15, (Fig. 4) which 25 may be termed the bumper proper, is of substantially the usual construction, curved horizontally and U-shape in vertical cross section. As said plate, 15, forms an approximate arch and is therefore non-flexible, it is preferably as short 30 horizontally as is practicable for the purpose. The upper and lower faces of said center bumper plate, 15, are spaced to embrace the bumper face strap, 14, and the four wood springs above referred to, and yet pass between the upper and 35 lower flanges of the end channel, 2, (see also Fig. 5) without undue friction, which upper and lower flanges therefore serve as a guide to permit the spring bumper to be pressed inward, and yet prevent the bumper from being forced upward 40 or downward.

The bumper side plates, 16, which may be two or more in number, are similar in cross section to the bumper center plate, 15, but relatively short horizontally, and preferably united to the 45 bumper face strap, 14, by the double countersunk rivet, 17, (at right in Fig. 4). The bumper side plates, 16, also embrace the wood springs and pass between the upper and lower flanges of the end channel, 2, as in the case of the bumper 50 center plate, 15, as previously explained.

Evidently with the said wood springs, the said bumper face trap, 14, with its attached bumper side plates, the wood spring blocks, and the bumper center plate, 15, all in place, the insertion 55 of the said four bumper bolts, 13-1 and 13-2, will only require the screwing on of the four bumper bolt nuts, 614 (Fig. 4), to hold the spring bumper in place during service. The removal of the four bumper bolt nuts, will permit the removal 60 of the entire spring bumper, and its replacement when renewed or repaired, or its replacement by some other similar form of spring or solid bumper.

65 Broken wood springs can be readily replaced by new ones; or a block or blocks may be placed in the center, between the spring, 11-1, and the vertical web of the end channel, 2, and of the same thickness as the end blocks, 12-1, thus 70 converting the wood spring bumper into a solid wood bumper.

The wood springs are preferably tapered to bend near their ends, instead of near the center bumper bolts, 13-1, thus minimizing the tend- 75

ency of the springs to break at said center bumper bolts.

In going around curves, in compression, the compressive haulage strain results in a sidewise thrust tending to force the bumpers to slide longitudinally along the face of the end channel. Hence the object in placing the two end bumper bolts at a substantial angle to the end channel, 2, is to tend to counteract this sliding tendency of the bumpers, which, however, is more directly overcome or resisted by means of the two end bumper plates, 18. These plates, 18, are U-shape in cross-section and extend between and are secured to the upper and lower flanges of the cross end channel, 2. The vertical connecting part of the end bumper plate, 18, is that shown in section in the right of Fig. 4.

As the wood springs are not designed to bend materially between the center bumper bolt holes, 20 they may be spiked or nailed or otherwise suitably attached together, thus forming practically a solid wood bumper when the spring bumper finally comes to rest against the cross end channel, 2.

25 There is actually less wood in the wood springs, than in the wood beam out of which a solid wood bumper is hewed. While the smaller sizes are also cheaper than the larger size solid member, the labor costs of the spring bumper about offset the saving in material, thus leaving the cost of the two substantially the same. For this reason, both bumpers are shown flexible in Fig. 1, although evidently one bumper may be made flexible and the other solid, if preferred.

30 While the foregoing end structure description applies to the end structure at either end of the car, the draw-bars are so associated with the end sill, 2, as to become parts of the end structure. At the rear end of the car, a rigid draw-bar is made a part of the end structure in a manner to also brace the end channel, 2. At the front end of the car, a spring draw-bar is made a part of the end structure in a manner to also brace the end channel, 2. The rigid draw-bar 45 at the rear end of the car and the spring draw-bar at the front end of the car will be described further on.

Traction truck bracing

50 It has been convenient, for the purpose of illustration, to show the flanges of the end channel, 2, (Fig. 5) for example, of such a width that it may be obvious that the bumper channel, 15, is suitably supported in working position, and yet 55 slide longitudinally of the car when the spring, 11-1, 11-2, 11-3, 11-4, is in compression, as when a trip of cars is being pushed uphill.

Where the service is severe, it is important to brace the end channels at or near the center, 60 thus obviating the necessity for excessive increase in the dimensions of the end channels. This center bracing incidentally serves other useful purposes. However, it is not wished to restrict the invention to center bracing as the only means of 65 taking care of the heavier haulage strains incident to more severe service; nor to the relative dimensions of end channel shown in the drawings, selected as convenient for purpose of illustration.

70 It has already been stated that the bumper deflector, 9-1, is joined to the upper part of the forward end channel, 2, whereby the entire upper part of that channel is braced or reinforced. It has also been stated that the floorplate, 7-3 (Figs. 1 and 2) is secured to the lower part of

the rear end channel, 2, whereby all the lower part of said channel is braced or reinforced.

As shown in Fig. 2, the draw-bars, 30-11, 30-12, reinforce the upper member of the rear end channel, 2. The lower member of said rear channel may be further reinforced by means of a strip of sheet metal, 130, also herein termed a lading bottom end member, riveted to the upper face of the rear floor plate or sheet, 7-3, the rear end of said strip of sheet metal abutting 10 against the lower vertical face of said channel, 2, at which point said strip may be bent upward, as shown, to give a better bearing (Fig. 2). The said strip of sheet metal, 130, is placed in the transverse center of the car and preferably extends 15 forward at least to the forward end of the upper draw-bar member, 30-11, in order that it may be suitably riveted thereto as shown (see also dotted lines, 130, Fig. 1).

The front end channel, 2, is preferably reinforced, top and bottom, in much the same way. As shown in Fig. 5, the inclined angle irons, 131, one on either side of the spring draw-bar, 30-1, 30-2, brace the upper flange of the front end channel against compression, in the same way 25 the rear draw-bar braces the rear channel. Said angle irons, 131, are riveted to the under side of the bumper deflector plate, 9-1, and abut, at their forward ends against the upper rear face of the front end channel, 2. The upper flange 30 of the front end channel is, as already stated, reinforced against tensile haulage strains, by the bumper deflector plate, 9-1, riveted thereto.

The lower flange of the front end channel is similarly reinforced against compression by the 35 horizontal angle irons, 132, one on either side of said spring draw-bar, 30-1, 30-2. In order in part to maintain the said horizontal iron, 132, suitably in place, it is riveted to a flat strip, 133, the front end of which is in turn riveted to the 40 under side of the lower flange of the front end channel while the rear end of said strip abuts against the front edge of the front bottom plate, 7-1. A connecting plate, 134, overlapping and riveted to both said strip and plate, 7-1, serves 45 also as a brace against tensile haulage strains.

The inclined angle iron, 131, and the horizontal angle iron, 132, may to advantage be riveted together at their overlapping rear ends as shown. Both the said angle irons may to advantage be 50 so placed as to form lateral guides for the said spring draw-bar, 30-1, 30-2. The lower horizontal angle iron, as shown, serves as the pin seat for the draw-bar pivot pin, 32. (Figs. 4 and 5.)

The thrust of the lading against the bumper 55 deflector plate, 9-1, when the car is being dumped endwise would tend to bend said plate in the direction of said thrust, were it not for the inclined angle bar supports, 131, previously referred to. The axle deflector plates proper, 60 9-2 and 9-3, (Figs. 1 and 7) should also be reinforced, preferably by similar inclined angle bar supports, 135, riveted on the under side of the said axle deflector plates, and also running parallel to the length of the car. 65

As shown in Fig. 2, the draw-bar composed of the bars, 30-11, 30-12, reinforces the upper member of the rear end channel, 2.

The swinging draw-bar housing hereinafter described, evidently is also well adapted to serve 70 as a compression brace for the end channel, and may be suitably attached to said end channel to enable said channel the better to resist the tensile haulage strains.

With suitable bumper top center bracing, the 75

channel reinforcing strap, 3, may be omitted for medium or light service.

Rigid draw-bars

5 Both the front and rear draw-bars may be either spring or rigid draw-bars, as may be desired, for any particular service. For general use however, in part on the score of economy, one spring draw-bar and one rigid draw-bar (as 10 shown in Fig. 2) is the preferred construction.

The simple form of rear rigid draw-bar, shown at the right in Fig. 2, consists of the upper member, 30-11, the lower member, 30-12, and the angle connecting bar, 51. The upper ends of the 15 rigid members, 30-11 and 30-12, are parallel to each other, and maintained the distance apart suitable for the service, by any suitable draw-bar filler, as 35' (Fig. 2). The draw-bar filler, 35', is retained in place by the rivet, 35'', passing 20 through both draw-bar members. At a suitable point from the upper rear end, the upper member is bent forward and downward, at say an angle of forty five degrees, until it reaches the car bottom, at which point it is again bent forward so 25 as to rest on the car bottom or car bottom bracing, to either of which, as the case may be, it is suitably riveted. Figs. 1 and 2 show said member resting on the plate, 130, and secured by rivets extending through the member and the plate, 30 130, and the floor plate, 7-3, as described under—
Traction truck bracing.

The upper rear end of the lower rear member, 30-12, rests on the upper face of the end channel reinforcing strap, 3, at the forward edge of 35 which it is bent downward, at right angles, so as to bear against the forward face of the rear channel and extend downward well past the vertical center of the said end channel.

The upper rigid member, 30-11, is so placed 40 that the forward and downward extension thereof bears against the right angle turn in the lower rigid member, 30-12, and thus forming an angle of approximately forty five degrees with the lower end of said lower rigid bar. The angle connecting bar, 51, is so bent that it fits neatly into this 45 forward and downward extending angle between the two rigid bar members, and is of such length that the forward leg of the angle connecting bar, 51, may be securely riveted to the sloping portion of the upper rigid member, while the 50 rear vertical leg of said angle connecting bar, 51, may also be securely riveted to the vertical portion of the lower member and also to the end channel, 5, all substantially as shown in Fig. 2. 55 Thus the upright parts of the draw-bar 30-12, and the angle bar 51, form vertical end thrust means.

Evidently, the upper rigid bar member as shown, may be made to utilize the strength of 60 the car bottom, 7-3, as well as the strength of the end channel, 2, in resisting the tensile haulage strains; whereas, when the haulage strains become compressive, the improved rigid draw-bar, as shown, serves equally as a most admirable brace to the upper flange of the end-channel.

The width between the I-beams, which preferably form the longitudinal side sills of the improved traction truck, will seldom be less than 65 say three feet, while the steel bottom should be about one quarter inch sheet steel, and thus equivalent to a bar of steel say four inches wide and say two and one quarter inches thick. With this bottom sheet properly riveted or otherwise secured in place in relation to the side beams, it 70 is evidently a most substantial element of

strength to which the bumper and draw-bar may be very properly attached and braced when desired.

Evidently the said rigid draw-bar may serve as a most admirable bumper brace for the top flange 5 of the end channel, in the center where it is most needed, for both compressive and tensile haulage strains, as herein designated, no other bracing for the said top flange being necessary, certainly not for medium and light service. For 10 these reasons the rigid draw-bar may also be correctly designated as of the reinforcing draw-bar type.

Bottom pivoted spring draw-bars

15

The double draw-bar has been selected for the purpose of illustration, but may be single as in Figs. 29 and 31. The rather simple front spring draw-bar, shown in Fig. 5, consists of the upper member, 30-1, and the lower member, 30-2, 20 preferably united by the double counter-sunk rivet, 31. The lower end of the upper member is looped around the draw-bar pivot-pin 32. Both the upper and lower members are preferably so bent that the draw-bar will come to rest, 25 when pulled forward, on the half-round filler, 33, which rests on the base plate, 34, secured to and arranged at the upper rear corner of the channel, 2. (Figs. 5 and 35.)

The upper and lower members (Fig. 5) begin 30 to separate at say forty five degrees, at the point where they pass around the upper edge of the said half-round filler, 33. The draw-bar filler, 35, is placed between the said upper and lower draw-bar members where they begin to spread, the said 35 draw-bar filler being of such width that the two said draw-bar members are the distance apart desired for the suitable operation of the link coupling held in place by the coupling pin, 36. The said draw-bar filler is retained in place by 40 means of the rivet, 37, passing through both the draw-bar members. The said rivet, 37, may also have a short section of pipe, 38, around it and between the draw-bar members to further insure the exact distance apart desired. 45

Both the upper and lower draw-bar members are so bent, when they are pulled to their extreme forward position, and thus rest against the said half-round filler, 33, the forward portions of said upper and lower draw-bar members are parallel 50 to each other and also parallel to the channel reinforcing strap, 3, upon which the lower-draw-bar member rests.

The coil spring, 39, is so placed about midway vertically of the end channel, 2, that the rear end 55 of the said coil spring bears against the nearly vertical portion of said double draw-bar. About midway between the said half-round filler, 33, and the draw-bar pivot 32 (as shown in Figs. 4 and 5) the said coil spring, 39, passes through the 60 end channel, 2, through the circular hole, 412, in the channel (see also Fig. 12), the front end of said coil spring bearing against the bearing plate, 40, attached to the inner wood spring, 11-1.

In order to maintain the said coil spring, 39, in 65 its proper relation to the several parts, a circular angle bearing plate, 411, is placed at either end of said coil spring. The coil spring pin, 41, is shown inserted in a suitable recess in said double draw-bar and in a corresponding recess in said bearing plate, 40, and through the centers of the 70 said circular angle bearing plates, 411.

The coil spring, 39, thus serves a double purpose, in that, under compressive haulage strains, it reinforces the spring action of the wood spring 75

bumper, while under tensile haulage strains, the said spring serves to give a spring action also to the double draw-bars. The hole, 412, in the end channel, 2, necessitated by the coil spring, (see Fig. 12) will not materially weaken said channel, particularly for light service.

With the lower end of the double draw-bar pivoted for bodily rocking, during such rocking there is a change of angular relation between the draw-bar and spring and the rear circular angle plate, 411, to accommodate which the face of the rear circular angle bearing plate, 411, is made suitably conical, as are the holes in which the coil spring pin, 41, rests, the middle portion 15 of the said coil spring pin, 41, being made of a larger diameter than the holes in the angle bearing plates, 411, so that the pin cannot drop out. (Fig. 4.)

The bumper deflector plate 9-1 (Fig. 5) is slotted in the center to permit the desired backward and forward action of the upper part of the double draw-bar. The lower pivoted end of the double draw-bar is held between parallel stationary guides, 132, provided in part for that purpose, and through which the draw-bar pivot pin, 32, is passed. Once the several parts are in place, the insertion of the said pivot pin will evidently insure their being maintained in working position during service; and the removal of the draw-bar pivot pin will permit the removal of the several parts.

Upper structure

The upper structure comprises the lading retaining walls and the side floors extending laterally from and supported by the side beams.

In order to gain capacity, the side lading body has heretofore been so placed below the top of the wheels as to require wheel hoods over the wheels to permit their rotation in service. This arrangement is seriously objectionable for several reasons, one of which is, the wheels cannot be removed until the axles are punched or pushed out, which is not always readily done. Then, too, when a car is derailed, workmen cannot, on account of the low sides, get under the car to rerail the car.

The belts or binders, usually three or four in number, are so bent and placed as to support and give the lading holding body its desired shape and position. These belts are usually all bent near enough alike, so that the car has substantially the same transverse cross section throughout.

With the improved traction truck, a large portion of what may be termed the lading holding body is that portion of the car outside, and usually above, the traction truck.

The improved wheel-recessed wing lading holding body, a, has a middle transverse cross section sufficiently high off the rails to permit the ready removal of the wheels, in the usual manner, without changing the position of the axles. This same transverse cross section is preferably maintained either way from the center to such a distance on either side of the wheels as will leave ample outward clearance for the wheels, without the hindrance offered by axle hoods. This also gives the workmen chance to get under the center of the car where work is needed to be done, in order to rerail the car. This arrangement also gives room between the wheels for the usual style wooden brake block, which cannot well be used in connection with wheel hoods.

As shown in Fig. 2, the improved lading hold-

ing body has, at each side of the car, a front belt, 150, a center belt, 150-1, and a rear belt, 150-2, (Figs. 2 and 3).

The lower, upright part of each belt rests flatwise against the outer face of the web of the adjacent I-beam, 1, and bears against the adjacent lower flange and against the adjacent upper flange of the I-beam. At said upper flange, each belt is bent outward, the middle belts, 150-1, being bent outward only far enough to be bent upward across the upper flange, and the other belts being extended horizontally from said upper flange farther than is the case with the belts, 150-1, as will be described further on. The part of each belt which lies between the I-beam flanges and against the web of the I-beam is secured to the I-beam by means of a transverse bracket plate, 156, lying against the outer face of the belt and being bent to lie against said web. Said bracket plate is secured by means of rivets, 157, extending through said plate and said belt and the web of the I-beam and through said plate and said web (Figs. 2 and 15).

The center belt, 150-1, is extended upward from the outer edge of the upper I-beam flange into a horizontal plane sufficiently high to clear the tops of the wheels the desired distance. Thence said belt is extended outward, horizontally to the desired lateral mine clearance. There it is bent upward to the desired vertical mine clearance.

The two parts of the lading holding body which extend over the wheels, on either side, (see Fig. 3), are usually termed the wings of the car. As it so happens, the top of the I-beam will, under usual conditions, be about as low as the wings of the car can safely be made. The front and rear belts, 150 and 150-2, are therefore preferably extended outward horizontally at the level of the top flange of the I-beam, similar to the special reinforced belt, 150-3, (Fig. 15) (this extension being outward as far as the outward extension of the belts, 150-1), and thence upward to the height of the belts, 150-1. Thus, in each of these four belts, 150 and 150-2, there is a saving of two bends compared with the belts, 150-1. Thus the outer, upright parts of the belts, at each side of the car, are in a common plane which is upright and parallel to the length of the car. And it is to be noted that the horizontal parts of the belts, 150 and 150-2, are approximately at the height of the upper flange of the end channel, 2, or the reinforcing strap, 3, resting flatwise on said flange; for said parts of said belts and said flange or strap are each approximately at the height of the upper flanges of the I-beams. This feature is to be further mentioned in connection with the provision for the discharge of the lading when the car is of the end-dump kind.

Owing to the difference in the heights of the wings of the improved lading holding body above the wheels and forward and rearward of the wheels (see Fig. 2), the wings may be said to be longitudinally recessed upward in the center, and may therefore be said to be wheel recessed. Owing to this longitudinal recess in the center, the sheet metal lining of the wings cannot well be made out of one piece bent to conform to the shape of the belts, but is preferably made out of say three strips of sheet metal; the upright, outside strip, 151, the center horizontal strip, 152, and the upright, inside strip, 153. (Figs. 2 and 3.)

The lower part of each upright, outside strip or sheet, 151, is preferably as long as the side beams and recessed to give the desired clearance for both wheels and having its lower edge resting on the three adjacent belts and rising to the height of said belts, as heretofore described. The center horizontal strip or sheet, 152, is preferably as long as the side beams and so bent that its outer, side edge will meet the lower edge of the sheet, 151, and will rest on the three belts.

5 The strip or sheet of metal made by recessing the outside sheet, 151, will evidently be of correct shape to serve as the inside strip, 153, so that the improved wheel recessed car wings do not involve any waste of sheet metal in the cutting.

10 The sheets, 151, 152 and 153, are joined to each other by angle irons, 154 and 155. These angle irons, 154 and 155, are bent to conform to the lower edge of the outside strip or sheet, 151, above described. The vertical flanges of the angle irons, 154, extend upward from their horizontal flanges, whereas, with the angle irons, 155, the vertical flanges remain below the horizontal flange (Fig. 3).

15 With the several parts suitably assembled, it evidently only remains to rivet or otherwise suitably attach the several parts (the belts and sheets and angle irons) together.

20 As above stated, the horizontal parts of the belts, 150 and 150-2, are at approximately the height of the upper flange of the end channels, 2. Hence the ends of the sheets, 152, and said channel flange, are in approximately the same 25 horizontal plane. Hence a sheet, a1, of parallelogram form may rest on the rear channel, 2, and the adjacent ends of the wing sheets, 152, and meet the outer sheets, 151, and be suitably secured to the adjacent members.

25 At the front end of the car, a door a2, of parallelogram form is similarly placed relative to the channel and the sheets, 152, and the outer sheets, 151, and attached to arms a3, placed beside the outer sheets, 151, and coupled thereto at a4, to 30 permit lifting the door, as by engagement of a hook a5, supported on the door, as already known in this art.

35 When the car is tilted and the door is opened, the lading will discharge over the bumper deflector, 9-1, and over the forward ends of the wing sheets, 152. The rear slope of said sheets is to be such as will allow rearward lading to 40 slide forward during dumping, as described of the axle deflectors.

45 From the foregoing it will be seen that the haulage strains, both tensile and compressive, are transmitted through the truck and not through the upper structure, the belts and the sheets of the upper structure containing only enough metal 50 to impart strength to support the lading, the upper structure being, therefore, adapted to yield to abnormal strains in excess of strains to be resisted for supporting the lading.

55 For convenience in designating or describing the position of the lading floor or lading bottom relative to the axles or the journals which are supported by the car wheels, the term "axle plane", is herein applied to the horizontal plane which cuts or is closely associated with said journals, the lading floor or a substantial part thereof being below that plane. In the particular form shown by the drawings, this "axle plane" cuts the side sills between the upper and the lower parts of said sills.

60 75 It is to be noted that the car floor or bottom is

so supported and secured in the body of the car as to adapt it to remain in stationary or fixed position relative to the "axle plane" during operation of the car—during the loading and transporting and unloading of the car, the unloading being effected by tilting the entire car bodily and discharging the lading from the car by the action of gravity. Accordingly it is to be understood that, as used in the claims, "stationary floor" means a floor which is supported and secured and 10 remains in position during operation or service as above described. Thus used, the term, "stationary floor" or "stationary bottom" excludes cars from which lading is discharged by gravity by displacing the floor relative to the axle plane. 15

Regarding the lading floor or bottom which lies entirely or in part below the horizontal "axle plane", the term, "sub-axle" floor or bottom is applicable and is so used in some of the following claims, that term being used to distinguish 20 from the old type mine cars in which the lading bottom is above and extends across the axles. The deflectors which guide the lading over the axles and to or over the end structure are to be regarded as parts of the car floor or bottom. 25

In mine car practice, the ends of the car are provided with means for joining or connecting the car to other cars to form trains or "trips". This means for joining cars is ordinarily mentioned as "coupling" for the cars. In these cars provision 30 is also made for taking impact or pressure when cars are driven or pressed against one another. Such means are ordinarily called "bumpers" or "bumper means". In this application several forms of means for performing these two functions are shown and described, the means for the two functions being in part combined structurally. To these means it is appropriate to apply the term, "bumper and coupling means", and in some 35 of the following claims that term is used with that meaning. 40

In mine cars of this general type, it is desirable to place the car axles sufficiently near each other to divide the length of the car into three parts, a middle part located between the axles and an end part reaching away from each axle, whereby the space between the wheels at each side of the car is relatively limited and makes what is termed a "short wheel base". For load distribution this 45 positioning of the axles is desirable. Producing a "short wheel base" by this positioning is also desirable, because, as already herein stated, such a car having a short wheel base can better traverse short curves in such rail tracks as are ordinarily in service at mines. Furthermore, placing these 50 axles to form a short wheel base, removes the wheels from the ends of the car where they will not interfere with the coupling and bumper means when cars are to be connected for operation as trains or "trips". By reference to the 55 drawings, it will be seen that in the improved car the axles and wheels are placed as above described. And this placing of the axles may be defined as placing them in upright transverse planes which are between the upright transverse middle plane 60 of the car and the ends of the car. It is also to be observed that an upright, transverse plane between either end of the car and the adjacent wheels, and near said wheels, will cut a part of the sub-axle lading floor or bottom lying below 65 the axle plane. Hence it is appropriate to define these wheels and axles as being grouped between two upright, transverse planes cutting portions of the sub-axle lading floor lying below the axle plane. 70 75

The foregoing discussion has included conditions and problems encountered in the construction and operation of mine cars, and has proceeded far enough to assemble parts to constitute a complete car embodying this invention.

Continuation of the discussion will relate further to such conditions and problems and to other forms of structure of parts adapted to be put into a mine car embodying this invention.

10

Capacity

In mining practice, the "out-to-out" dimensions of the mine cars are definitely limited by the conditions existing underground. Hence the principal and fundamental object of any improved mine car is the attaining of the greatest lading capacity practicable for a given set of "out-to-out" dimensions, which, as in railroad work, is absolutely essential to attaining the lowest possible operating costs.

In mining it is rather the vertical and transverse "out-to-out" dimensions that are limited by the underground conditions, although the lengths of the mine cars are also to some degree limited by the working conditions. For the same vertical and transverse out-to-out dimensions, the improved traction truck will be seen to give quite a material gain in capacity.

When working thin veins of coal, in order to use cars of any substantial capacity, the common mine cars having plank floors must employ planks made so thin that the cars cannot be made more than say ten feet over all length, in order to avoid the excessive bending or breaking of the bottom planks. However, a twelve foot car is thoroughly practical otherwise, and self evidently the improved traction truck can be made any length that can be gotten around in the mines. The twelve foot car for thin veins will hold closely twice as much as the old style all wood ten foot car, thus cutting haulage costs into halves while reducing other items of cost quite materially owing to the larger tonnage that can be handled in a given number of hours, sufficient to pay for an entire new mine car equipment in a relatively short time.

Cars that can be made high enough off the rail to admit of thick wood bottoms are now made twelve feet in length, but there are a number of reasons for believing that fifteen foot cars will be found thoroughly practicable as soon as it is demonstrated that their construction can be made such that they will stand the service. A few fifteen foot cars have already been built and are in service. Even with thick wood bottoms the longer car shows proportionately greater gain in capacity.

Further: traction truck

With the old type all-wood car, the bottom of the bumper is the top of the plank forming the car bottom, which latter rests above the axles, so that the top of the bumper is quite high off the rail. With this traction truck, the bottom of the car is brought down as close to the track as is otherwise practicable, the bumper being, therefore, to protect this bottom equally close to the track. Therefore, in order that the truck may work in with other mine car equipment, the bumper should be as high off the rail as the old type bumpers and also as close to the track as the car bottom, thus giving about twice the bumper depth heretofore in use; which, however, is manifestly of itself an advantage, in that it will

materially reduce the tendency of the bumpers to slide under or over each other.

Belts

The recess in the side of the I-beam formed by the top and bottom flanges offers a convenient method for reinforcing the front and rear belts.

The simplest form of reinforcing consists in turning back the lower end of the belt, 150—3, (Fig. 15), up until it again meets the outer horizontal portion of the same, to which it may be suitably riveted.

The belt however, may be attached to the inside of the I-beam, (see 150—5, Fig. 16), and then bent upward around the inner edge of the upper flange, and thence back again horizontally. A secondary reinforcing belt 150—6, is preferably riveted to the outside of the I-beam, and then bent outward, at the upper flange, to meet the main belt, to which it is then bent.

The front and rear belts (see 150—7, Fig. 17) may also extend down from the top of the lading holding body wings, to the level of the lower I-beam flange, then be bent horizontally inward to meet the junction of the said lower flange and the web of the I-beam, and then bent upward to rest against the said web, to which they are securely riveted. A secondary end belt, 150—8, may be attached next the angle iron, 6, (see also Fig. 4), which rests against the web of the I-beam, then bent out, up, and down over the upper flange, at say an angle of forty five degrees, until it meets the outer horizontal portion of the front or rear belt as the case may be, to which it is then securely riveted.

The end belts, when attached to the outside face of the I-beam web, have preferably, over the outside of the attached portion, a bracket plate, 156 (see Fig. 15). The belt rivet, 157 passes through the said bracket plate, the said belt, and the said I-beam web. This bracket plate is bent inward, at the rear vertical edge of the belt, (see Fig. 2), until it meets the face of the said web, to which it is again riveted as shown. The middle belts are provided with a similar bracket plate, 156—1.

Variations: spring bumpers

The spring bumper however, may be provided with a metal spring, 19 (Fig. 9) for the purpose of reinforcing the action of the wood springs, as shown.

This auxiliary spring, 19, can be of various forms and constructions, although in Fig. 9 is shown a leaf or semi-elliptic spring backing and parallel to the wood spring, and located beh'nd the central portion thereof. If desired, a spring bearing plate, 20, can be employed equal in width to the wood springs, and resting on the convex center of the said wood springs.

Evidently by reducing the number of the wood springs, room may be left for one or preferably several coil springs, between the wood springs and the forward face of the end channel web. Where metal bumper springs are used, evidently the wood springs may be replaced by a solid wood bumper, somewhat similar to that in Fig. 27 or by a metal or ribbed metal bumper proper.

Solid bumpers

Evidently the space between the bumper face strap, 14, (Fig. 4), and the front vertical face of the end channel, 2, may be filled with a solid wood beam hewed to fit within the space specified, the coil spring shown being omitted. This

70

75

will give a solid wood center bumper, somewhat similar to the solid wood side bumpers shown in Fig. 27, and next described.

All the bumpers previously described, may be termed center bumpers. What are termed side bumpers are used rather extensively today, but are rapidly being superseded by the center bumpers.

The single draw-bar still in use extensively fits practically level with the top of the bumper, which therefore is necessarily recessed, (see Fig. 27), in order to permit the use of the coupling clevis, 21, (Fig. 31). This construction is what in practice is termed the side bumper arrangement.

The side bumpers shown in Fig. 27, consist of two wooden blocks, 22, fitting between the side bumper sheathing, 23, (Fig. 28), and the front face of the end channel, 2; and these blocks are spaced apart to provide ample clearance between the draw-bar and adjacent end faces of said blocks.

The wood side bumpers are preferably held in place by the center bumper bolts, 13-3, and the end bumper bolts, 13-4, and covered with the bumper sheathing plates, 23, which fit between the upper and lower flanges of the end channel. The outer corners of the wooden blocks and their sheathing plates are curved, so as to admit of the cars readily taking the curves. The plates, 23, are held in place by the bolts, 24, inserted after the bumper blocks and sheathing plates are in place and the wood blocks are held in place against lateral thrust, by the outside end bumper plates, 18, and the inside end bumper plates, 18-1, and the draw-bar is riveted to the end channel, 2, by the king rivet, 25.

Even flexible or spring bumpers have a rigid backing in order to take care of the final impact of one car against another, which rigid backing may be built up or braced, preferably, at least in part, by suitable connections with the sheet metal bottoms, which are admirably adapted for that purpose, so as to meet the requirements of any class of service, even the most severe.

The flexible or spring bumpers may consist of vertical wood springs, a combination of wood and metal springs, or of a solid wood bumper in connection with wood or metal springs. A solid wood bumper may, of course, be used with the improved traction truck.

Variations: bottom pivoted spring draw-bars

As will be evident from Fig. 5, a coil spring in line with the vertical center of the bumper will evidently be quite close to the draw-bar pivot pin, thus giving the draw-bar a great leverage against it, reducing, for a given draw-bar play, the force of the spring action. In order to increase the force of the spring action, a separate leaf or semi-elliptic draw-bar spring, 42, Fig. 9, may be introduced as high up, as the bumper deflector plate, 9-1, will permit.

A spring bearing plate, 43 (Fig. 13), with the rear lower half sloped to fit extreme rear position of the spring draw-bar, may be introduced between the draw-bar spring, 42, (the same as in Fig. 9) and the upper vertical portion of the lower draw-bar, 30-4, the spring pin, 44, serving to maintain the said bearing plate in position. In order that the said spring may have a straight line action, a link, 45, may be inserted in the slotted lower pivot end of the upper draw-bar, 30-3; a secondary draw-bar pivot pin, 32-1, 75 passing through the forward portion of the said

draw-bar link, and through the spring bracket, 46, which latter serves the double purpose of supporting the said draw-bar spring, and also acting as a bumper compression brace; (see also 46-1, Fig. 9). In order to keep the draw-bar from working upward, a draw-bar catch, 47, (Fig. 13) may be riveted to the rear lower vertical portion of the upper draw-bar, the lower portion of said catch being extended rearward, as shown, to engage the forward edge of the horizontal plate, 10 48, riveted to the sheet bottom, 7-4, of the car, of the side dumping type.

The right line action of the draw-bar spring, 42-1, (Fig. 29), may also be assured by means of the line pin, 49, attached to the upper vertical portion of the draw-bar, 30-5, by means of the strap, (see dotted lines 50), the curved portion of said strap resting in a corresponding recess in the spring bearing plate, (see dotted lines, 43-1). The said line pin moving in a horizontal slot in 20 the bumper bracing; the draw-bar pivot pin, 32-2, working in a vertical slot similarly placed, so as to permit the vertical motion necessary to permit the horizontal motion of the said line pin.

Center pivoted draw-bar

The center pivoted draw-bar, shown in Fig. 34, is the preferred form of pivoted draw-bar. What may be termed the draw-bar lever arm, is the distance from the coupling pin, (see 36, Fig. 5) 30 to the draw-bar pivot 32. The draw-bar lever arm, in the case of the center pivoted draw-bar, may be said to be roughly, only about half that of the bottom pivoted draw-bar, while the spring lever arm may be said to be nearly twice as great. 35 It therefore follows with the center pivoted draw-bar, a given size spring will have fully three times the range of action, that it can have with the bottom pivoted draw-bar, for any given amount of motion of the forward (left, as shown in both 40 Figs. 5 and 34) end of the center pivoted draw-bar.

Where the tensile draw-bar strains at right angles to the upper part of the center pivoted draw-bar, the leverage against the coil spring 45 would be say as 3 to 2. Owing, however, to the relatively slight angle between the upper part of the draw-bar, in its highest position, and the horizontal draw-bar tensile strains or "pull", the leverage in favor of the spring, at the first instant, will be say 3 to 1. As the draw-bar is pulled more and more nearly horizontal, the leverage in favor of the draw-bar spring becomes greater and greater; it requiring an almost infinite horizontal pull to bring the center-pivoted draw-bar to a dead level. The center pivoted draw-bar is therefore, for coil springs of usual sizes for the purpose, a cushioned device for almost any pull, that can occur in practice.

With the center pivoted draw-bar, (Fig. 34), the horizontal or nearly horizontal portions of the draw-bars above the half round filler, 33, forming the draw-bar pivot, may be termed the draw-bar proper while the portions of the draw-bar below the said pivot point, may be termed the draw-bar 65 spring lever arm.

As shown, in Fig. 34, the upper and lower bars, 30-6 and 30-7, respectively, are preferably welded together, at their lower ends, the draw-bar pivot block, 52, is preferably welded to the upper 70 forward face of the more nearly vertical portion of the lower draw-bar, 30-7, in such a position as to form, with the bend in the draw-bars, approximately a half circle, to correspond to the half round filler, 33. In order to increase the strength 75

- of the bend in the draw-bars, a flat filler, 53, is preferably inserted between the two draw-bars at the bend, having been first bent to conform to the said bend.
- 5 The spring arrangement is substantially that shown in Fig. 5, with the bottom pivoted draw-bar. The coil springs, 39-1 and 39-2, act against the two circular angle bearing plates, 41-1, held in place by the coil spring pin, 41-1, which passes 10 through a horizontally U-shape bridle, 531, riveted between the bumper braces, and against which bears the rear angle bearing plate. The rear end of the coil spring pin, 41-1, has an annular groove around it, so as to receive the slotted upper U-shaped end of the coil spring pin key, 532, attached by the key bolt, 533, to the said bridle, so as to be readily removable. The forward end of the said coil spring pin is held in place by the conical aperture in the lower end of the draw-bars. With the several parts suitably assembled, it is evidently only necessary to insert the coil spring pin key, 532, and its bolt, 533, in place, when the center pivoted spring draw-bar is ready for operation.
- 25 The half round filler, 33, and its base plate, 34-1, (see also Fig. 5), shown as separate parts merely for the purpose of better distinction, are preferably welded together, the said base plate being riveted to the rear vertical face of the end channel; with the reinforced bend of the improved center pivoted draw-bar there should be little occasion to remove the same. It is however, advisable, to leave a slot, 534, in the center of the upper sloping face of the bumper deflector plate, 9-1, suitable to permit the removal of the said draw-bar; this slot being otherwise closed by the removable plate, 535, to prevent the lading falling through.

Swinging draw-bars

- 40 The swinging draw-bar shown in Fig. 18 has one feature in common with the center pivoted draw-bar just described, in that the lower ends of the upper and lower bars, 30-8 and 30-9, are preferably welded together. In case of the swinging draw-bar, however, this lower welded (forward as shown) end is forged into a round coil spring spindle, 30-10, which passes through the center of the double coil spring, 30-8.
- 50 The swinging draw-bar may also be said to be a pivoted draw-bar, as shown, in that it passes through a hole in the rear U-shape pivot bridle, 551 (Fig. 18), riveted between the vertical sides, 552, of the swinging draw-bar housing shown in 55 section at right angles to the draw-bar coil spring spindle in Fig. 19; the said hole being only as much larger than the said spindle as will permit the slight swinging motion required.

- 60 The said coil spring may bear against the said pivot bridle, 551, at its rear upper end, bearing at its lower forward end against the bearing thrust plate, 553, having a circular face plate adapted to receive said coil spring, together with a hollow cylindrical body adapted to receive the draw-bar spring spindle, as shown. The lower forward face of said hollow cylindrical body bears against the face plate, 554, which in turn transmits the spring thrust to the spindle key, 555, which in turn transmits it to the draw-bar 70 spring spindle.

- 75 Evidently, the said coil spring will cushion the draw-bar pull. The said hollow cylindrical portion of the bearing thrust plate, is passed through a hole in the forward U-shape bridle, 556, also riveted between the vertical sides, 552, of the

swinging draw bar housing; said hole being only enough larger than the outside diameter of said hollow cylindrical portion to admit of the necessary play; said face plate being enough larger than this hole that it may, when resting against the forward bridle, 556 satisfactorily transmit to it, without failure, any tensile draw-bar strains.

The draw-bar housing may consist of two vertical plates, 552 (Figs. 18 and 19) one on either side of the double coil spring, 39-3, and having their lower edges bent outward at right angles, to fit the rear bottom plate, 7-3, and riveted or otherwise suitably attached to the same; the sides of the vertical plates being cut to suitably enclose the said swinging drawbar without unnecessary loss of lading space; the housing cover, 557, being bent to conform to the sides of the vertical plates, 552, to which said cover is suitably attached, as by bolts and nuts.

In order to prevent the sliding motion of the draw-bar gradually cutting into the channel reinforcing strap, 3, the draw-bar roller, 558 (Fig. 18) may be introduced, so placed that the draw-bar comes to a bearing on same, before the draw-bar reaches its extreme rear (as shown) position, (see dotted lines, 30-10), which is the position of greatest downward pressure.

Evidently what has heretofore been termed pivoted draw-bars may also be termed swinging draw-bars, as distinguished from spring draw-bars, heretofore in use, in which the action is strictly right line.

Variations: rigid draw bars

Fig. 2 shows a rigid draw bar arrangement, as applied to the rear end of an end dump mine car. As applied to the front end of an end dump car, the rigid draw-bar, in addition to reinforcing the upper flange of the end channel against compression, may be utilized to also support the front deflector plate, 9-1, against the thrust of the lading while being dumped.

The construction shown in Fig. 2 may be varied largely. For instance, the preferred construction, as applied to the front end of the car, is illustrated in Fig. 14; the lower bar, 30-14, resting, at its forward end, on the channel reinforcing strap, 3, is extended horizontally rearward, until it just passes over the bumper deflector plate, 9-1, at which point it is bent downward to conform to the slope of the said deflector plate, and resting thereon, as far as desired, but preferably, for heavy service, extended the full length of said deflector plate, until it reaches the forward bottom plate, 7-1, (Fig. 2) and then again bent and extended over the same sufficiently that it may be securely riveted to the same, as in the case of the rigid draw-bar shown in Fig. 2.

The rear end of the top bar, 30-13, (Fig. 14), rests on the top of the upper sloping portion of the lower bar, leaving the lower bar, however, at the point at which the lower bar turns horizontally forward along the top of the end channel; the said upper bar passing on upward and forward, as shown, until it reaches the height necessary to give the clearance between the forward ends of the two bars, desired for the operation of the coupling device.

In the angle extending downward and rearward from the upper rear corner of the channel reinforcing strap, is placed a similar angle connecting bar, 51-1, at its front face bearing against the rear vertical face of the end chan-

- nel, the other leg of said angle connecting-bar bearing against the under side of the bumper deflector plate, 9—1, and immediately under the two bars just described.
- 5 Evidently then the upper forward portion of the deflector plate, in the center, is held between the bars and the angle connecting bar. Rivets passed through the four parts mentioned, as shown, will bind the same so as to form a 10 workmanlike reinforcing rigid draw-bar. The forward vertical leg of the angle connecting bar should be riveted, as shown, to the vertical rear of the end channel to hold the angle connecting bar rigidly in place under stress.
- 15 The construction shown may also be otherwise varied for the purposes indicated.

Center draw bars

With the center draw-bars shown in Figs. 28 20 and 31, the strength of both the top and bottom flanges of the end channel is utilized to resist the tensile haulage strains, instead of only that of the top flange, in the case of the top draw-bar, which latter involves what is termed in mechanics, eccentric loading, which also tends to rock the parts loose. For a given desired tensile haulage strain, therefore, a lighter weight end channel can be used, as the strains are then straight line instead of eccentric. The center 25 draw bars are however, in a less convenient position for coupling, and can only be used in new mines where all cars are of this type.

The double center draw-bar, as shown in Fig. 28, is preferably made from a flat bar of iron, so 30 bent as to form the upper bar, 30—14, and the lower bar, 30—15, the bend in the same being connected to the center of the vertical web of the end channel, by the rivet, 25.

The center draw-bar may also be a single draw-bar, (see 30—17, Fig. 31), similarly provided with a suitable coil spring spindle, also placed in the vertical center of the end channel.

Automatic couplings

45 The improved traction truck particularly readily admits of automatic couplings, similar to the Master Car Builders' automatic coupling, 58 (Fig. 38), which may have a broad base, 58—1, by means of which it may be riveted to the forward vertical face of the end channel, 2, by means 50 of the rivets, 581.

Variations: rigid axle boxings

This inner reinforcing plate, 61, (Figs. 7 and 8) 55 shown as wrought plate may be replaced by a somewhat similar inside axle boxing, 62, (Fig. 20), with which the axle boxing interlocks, as in the case of the wrought reinforcing plate, 61.

The axle bearing may be bushed in the usual 60 way with say a brass bushing, 63, (see Fig. 20) preferably extending the full length of the axle bearing and fitting, at its outer end, in a suitably prepared recess therefor.

Cutting a hole in the web of the I-beam sufficiently large to admit of the insertion of the inner extension of the axle bearing, as previously explained, necessarily somewhat reduces the strength of the I-beam at this point. This reduction in the strength of the I-beam may be made 70 considerably less without reducing the pin interlocking value of the axle boxing, by omitting the inward extension of the axle boxing and placing the interlocking feature at say the two extreme end axle boxing rivets, 64 and 65 (Fig. 6) thus 75 forming my improved end or bolt interlocking

axle boxing. The face plate, 60—4, (Fig. 22), has an inward cylindrical extension, 60—5, surrounding and concentric with said end rivet, 64—1, which therefore may be termed the bolt interlocking extension; the inward cylindrical 5 extension of said face plate passing through holes in both the web of the I-beam and through the inside axle boxing face plate, 62—1, just large enough for that purpose.

The length of said inward cylindrical extension 10 of said plate is made such that the rivet, 64—1, will just bind the several parts together as tightly as may be desired.

The same construction may be employed for the rear end rivet, 65 (Fig. 6). The sum of the 15 double pin shearing values thus obtained may be made actually greater than that obtained by the inward extension of the axle boxing as in Fig. 8, while only necessitating a hole in the web of the 20 I-beam, sufficiently large for the insertion of the axle, 66, (see Fig. 23).

Swinging axle boxings

The flexibility of the old type all-wood car is a 25 distinct advantage, in one respect, in that it permits practically at almost all times, full contact of all four wheels with the track, even in the case of a quite uneven track, a certain amount of which exists in all large mines. With all steel cars as at present constructed, in the case of uneven track, 30 often only three wheels are in contact with the rails, thus resulting in derailment, and consequent loss of time. Again, with all steel cars, the frames sometimes become sufficiently twisted, in wrecks, that on level track only three wheels are 35 in contact with the rail, thus rendering the car unfit for service. The swinging or drop axle boxing has been devised to permit the contact of all four wheels in case of either uneven track or of somewhat twisted trucks.

40 It has been proposed to accomplish the same purpose by means of vertically elongated axle bearings, semi-circular at the top and bottom, to fit the axle. With this arrangement, when the wheel hits the horns of the dump, the axle practically touches the axle bearing at but one point, and therefore necessarily, in time, will become badly battered and scarred.

In operation, the swinging or drop axle boxing 45 is preferably pivoted at the forward end, the rear end having the amount of vertical play that may be necessary to give the axle, roughly mid-way between, the desired amount of vertical play to maintain contact between the wheels and the rail, under reasonable conditions, thus permitting 50 the axle bearing to fit the axle, as is otherwise desirable.

The swinging axle boxing consists preferably of the combination of substantially what has heretofore been termed the end or bolt interlocking 60 axle boxing, now termed the outside axle boxing, together with a similar inside axle boxing; the inner and outer axle boxings being suitably connected together, to act as a unit, either of which 65 may be interlocked with the other.

Fig. 24 shows an inside view of the inside swinging axle boxing, 62—2, the extreme left rivet, 64—2 (Fig. 24) being the pivot pin or bolt, which is therefore made as large as is otherwise practical, and designated as the king pin or bolt. The 70 extreme right rivet, 65—1, holds together the rear ends of the said inside axle boxing and of the outside axle boxing face plate, 60—6 (see Fig. 26).

Fig. 30 shows the holes in the web of the I- 75

beam designed to give the maximum interlocking shearing value, for a given vertical wheel play, and the corresponding maximum net strength of the I-beam, the axle hole, 80, being between the 5 king bolt hole, 81, on the left, and what may be termed the swinging bolt hole, 82, on the right. The axle hole, 80, may be made as a vertical slot with the upper and lower ends semi-circular, and of a diameter equal to that of the axle, as shown. 10 The diameter of the king bolt hole, 81, should be equal to the vertical depth of the axle hole 80, see dotted lines 83. This gives the outside diameter of the king bolt interlocking extension 65, (Fig. 22). 15 The vertical depth of the axle hole 80, (Fig. 30), also controls the vertical depth of the rear axle boxing or swinging bolt hole 82, which should be the same, see dotted lines 83. The horizontal distance of the rear boxing hole 82 from the axle 20 hole 80, as shown in Fig. 30 is the same as the distance of the latter from the king bolt hole 81. Therefore, the vertical play of the rear boxing hole will be twice that of the axle 68. If therefore, there is deducted from the diameter of the 25 king bolt hole, twice the vertical axle play, there is obtained the outside diameter of the rear interlocking inward extension of the axle boxing around the rear axle boxing rivet 65-1, (Fig. 24), also termed the axle boxing swinging rivet. 30 With the swinging axle boxing, the upper edge of the axle boxing face plate, as well as the upper edge of the inside axle boxing should rest against the upper flanges of the I-beam, when the swinging axle boxing is in uppermost position (see 60-6 and 62-2, Figs. 24 and 26), there 35 being a space between the lower edges of the swinging axle boxings and the lower I-beam flange equal to at least the maximum vertical play of the axle boxings (see Fig. 26). The dotted lines in Fig. 24 show the swinging axle boxing in its extreme lower position. 40

In Fig. 30, within the axle hole, 80, the two positions of the axle, 66 (Fig. 25) are shown by the dotted lines, 66-1, the two extreme positions 45 of the rear axle boxing rivet, 65-1, being similarly indicated.

With the swinging axle boxing, more particularly, rivets are to be preferred to bolts and lock nuts, while cast iron is much preferable to 50 cast steel, on account of the readiness with which it may be obtained, as well as on account of the lower cost. A short section of wrought iron pipe, 84 (Fig. 22) may be put around the heated king bolt shank, both of which are then inserted in the 55 king bolt hole. A wrought washer, 85, may then be placed on the king bolt shank, and thus resting on the short section of pipe just mentioned, the length of which may be made such, if the king bolt be now headed in the usual way, on the 60 right as shown, that the cooling strains of the king bolt rivet will be taken up by the said short section of pipe, thus avoiding the danger of cracking the cast iron, and yet the bearing may have any amount of (horizontal as shown) play, 65 that may be desired.

The swinging axle boxing may have at least two other rivets, 86 (Fig. 24) near the top, in order to prevent the upward thrust of the axle from forcing the upper edges of the axle boxing 70 outward from each other, owing to the slight slope of the under sides of the I-beam flanges. These other rivets preferably also have short sections of wrought pipe and wrought washers, as in the case of the king bolt, the holes in the 75 I-beam web therefore being suitably slotted, to

allow the necessary vertical play, substantially as shown.

Self evidently, however, in so far as inequalities of track are concerned, only one pair of axle 5 boxings, preferably the rear axle boxings, need be of the swinging or drop type. Even for heavy service, the front axle boxings may be made rigid cast steel axle boxings, and the rear axle boxings, swinging cast iron axle boxings.

Variations: axle tubes

10

The axle tube, 100-1, Fig. 21, is not rigidly connected with the axle boxing, (as in Fig. 20), but is maintained in place by means of an annular collar, 102, on either end, bearing against 15 the vertical inner face of the inward extension, 60-7, of the axle bearing. This form of axle tube, which may be termed the loose axle tube, should be bushed (see 63-1, Fig. 21) with an annular bushing similar to that shown in Fig. 20, 20 inserted in either end. The loose axle tube is free to rotate, similar to the loose axle, so that if bushed, the bushed bearing may wear at least somewhat uniformly all around, and it has another advantage in that it admits of a relatively 25 simple form of spring wheel truck.

Axle tube spring truck

One of the material advantages of the swinging axle boxing, is that it readily admits of spring 30 wheel trucks, which will be particularly desirable, with a large mine car containing a considerable tonnage of coal. With bushed loose axle tubes passing through swinging axle boxings, it only becomes necessary to provide a suitable spring 35 action cooperating with the axle tubes, to secure a practicable form of spring wheel truck, which may therefore be termed axle tube spring trucks. The spring operating mechanism is, preferably, placed in the center of the axle tubes, one spring 40 operating mechanism therefore serving to operate equally the wheels on either side of the same.

As shown in Figs. 24, 25, and 26, the bushed loose axle tube, 100-1, operates the swinging axle boxings through which it is passed in either end. 45 Two tube bands or belts, 103, which pass over the axle tube, are made long enough to also pass under the spring lever pin, 104. The leaf or plate spring, 105, shown in Fig. 24, compressed flat, as by the weight of the car and its lading, has, 50 when not compressed, its concave side upward, the ends of said spring resting on the under side of the sheet metal spring plate, 106 (Fig. 32), the sheet metal spring plate being maintained in place by the angular brackets, 107, between it and the under side of the axle deflector sheet, 9-2.

The under side of said spring, 105, rests on the angular spring bearing plate, 108 (Fig. 24) flat on its upper side to fit the spring, but with the under sides sloping downward toward the 60 center so as to fit in a corresponding recess in the free end of the spring lever, 109.

The two tube bands, 103, are placed on either side of the spring lever, 109, as shown in Fig. 25, the latter being at the center of the bushed loose 65 axle tube, 100-1.

The spring lever, 109 (Fig. 24) has its forward end bent down under the bottom of the forward vertical part of the deflector plate, 9-2, where it is then again bent back up over the rear edge 70 of the forward bottom plate, 7-1, slightly recessed for that purpose. This bent forward end of the spring lever thus becomes the lever pivot, the opposite or free end of the spring lever having a vertical play at least equal to the amount of 75

the spring action. The portion of the spring lever immediately under the axle tube, is swelled sufficiently to permit the spring lever pin, 104, to pass through its center. With the several parts 5 suitably assembled, it evidently then will only be necessary to insert the spring lever pin, 104, in the two tube belts, 103, and in its hole in the spring lever, 109, the cotter pin, 110, then serving to maintain the several parts in their working 10 positions.

The spring, 105, when released from its compressed position shown in Fig. 24, as by the wheels passing over an abrupt drop in the track, will force downward the free (right as shown) end of 15 the spring lever, thus also carrying downward the lever pin, 104. Owing to the action of the axle tube bands, 103, the loose axle tube, 100—1, and its contained axle, 66, are also coincidentally forced downward, the positions of the several 20 parts being shown by the several dotted lines in Fig. 24.

Swinging tube spring truck

The swinging tube spring truck shown in Fig. 25 32, which does not require axle tubes, is materially simpler than the axle tube spring truck, which latter nevertheless is evidently also a swinging spring wheel truck. The essential point of difference between the axle tube spring truck, 30 and the swinging tube spring truck proper, shown in Fig. 32, is that in the latter the swinging axle boxing is operated, not by the axle tube, but preferably by a bent special swinging tube, as stronger and lighter, which however may be replaced by a 35 bar or other equivalent device.

The swinging tube, 120 (Fig. 32) is preferably placed immediately under the center of the spring, 105, of the same construction as the corresponding spring of Fig. 24, and bearing up against 40 the same kind of sheet metal bearing plate, 106, maintained in place by the angular brackets, 107. A suitable spring bearing block, 121, is placed at the center of the spring, 105, the said bearing block being flat on its upper side and concave longitudinally on its under side, to conform to the 45 curvature of said swinging tube.

The swinging tube, 120 (Fig. 32), at either end, is passed through the vertical face plates, 60—8 and 62—3, respectively, of outer and inner axle boxings, but not rigidly connected to the same. Said swinging tube may have an annular collar, 122, on either end, next to the face plates of the inner axle boxings, to maintain said swinging tube in the desired position. With the several 55 parts suitably assembled, evidently the insertion of the spring bearing block will hold the several parts in the working position.

Fig. 36 shows an axle boxing, 60—8, in part specially designed for the swinging tube spring truck 60 and in part designed to obviate the use of the secondary axle boxing rivets, 86, (Fig. 24) thus avoiding the holes in the I-beam necessitated thereby, see Fig. 30.

As shown in Figs. 32 and 36, the outside axle 65 boxing, 60—8, has a vertical rib, 60—9, immediately over the axle bearing proper, which transmits the upward thrust of the axle to the upper flange of the I-beam above, or still better to that portion of the I-beam bridle, 138, which extends 70 back under said upper I-beam flange, and which is planed off so as to give a horizontal bearing to said vertical rib, 60—9, said bridle extension being also riveted in place, as shown.

In order to give the greatest leverage possible 75 for the swinging tube, 120 (Fig. 32), it is prefer-

ably placed at the extreme end of the axle boxing opposite the king bolt pivot, 64—2. The swinging rivet, 65—1, may thus be placed between the axle and said swinging tube, 120, substantially as shown in Fig. 36, and thus giving the maximum 5 strength of the several parts, for a given reduction of the strength of the I-beam, 1.

The lower head of the rivet, 101 (Fig. 32), in conjunction with the similarly recessed upper face of the vertical rib, 60—9 (Figs. 32 and 36), of 10 the outside axle boxing will evidently serve admirably to hold said vertical rib in the desired position, when the same bears against the under side of the turned under tapered end of the I-beam bridle, 138—2. 15

The outside axle boxing may be provided with the usual oiling hole, 67, (Fig. 36) as previously explained. The face of the inside axle boxing, 62—4, may have an oiling interlocking extension into the outside axle boxing which will evidently 20 serve admirably to hold the vertical rib in the desired position, when the same bears against the under side of the turned under tapered end of the I-beam bridle, 138—2.

In addition to the usual oiling hole, 67, above 25 referred to, the said oiling interlocking extension may also be provided with its own special oiling hole, 67—1 (Fig. 36) and suitably connected with the axle bearing, but on the inside of the I-beam, 1, (see Fig. 2).

The rear end of the outside axle boxing, 60—8 (Fig. 36) may be an arc of a circle swung from the king rivet, 64—2, and conforming to the forward face of the axle boxing stop block, 123, riveted to the web of the I-beam so as to permit 35 the swinging action of the axle boxing, and yet also to take the dumping shock off the king rivet, in part or in whole, as desired. The curved forward face of said stop block is sufficiently re-entrant to keep the axle boxing face against 40 the vertical web of the I-beam.

Variations: axle deflector supports

In the case of the swinging axle boxing, the crown of the arch of the axle deflector plate will 45 be unsupported by the inner axle bearing, at such times that the wheels do not happen to be in their extreme upper position. With swinging axle boxings, the I-beam bridle, 138 (Fig. 10) 50 previously described, will serve the purpose, particularly if the I-beam angle brace is also used.

Wheel brakes

A number of otherwise good wheel brakes are 55 practically undesirable since, owing to their location incident to their design, they are quickly rendered unserviceable by being broken or bent through contact with mine obstructions. The recessed wings of the improved lading holding body offer a most secure place for the wheel 60 brakes and hence may be cited as one of the advantages thereof. The upper outside angle of the I-beam between the upper part of the web, and the upper flange offers a most secure recess for a rolling side brake rod, where it is safe 65 against almost any kind of injury.

The wooden brake block, 170, shown in the dotted lines (Figs. 2, 3 and 15) and the rolling side rod (see dotted lines 171, Fig. 15) and its bracket, 172 (see dotted lines, also Fig. 33) are 70 old, with three exceptions. The said rolling side rod has heretofore been placed in a position corresponding to the inner top bend of the middle be't, 150—1 (Fig. 3) so that the forward 75 brake block rod fulcrum, 171 (Fig. 15) comes on

top of said wooden brake block instead of below the said brake block, as in the improved brake rigging, and as shown in Fig. 15, which is due to the relatively low position of the I-beam.

5 With the improved brake rigging, room is preferably left between the rear belt, 150-2 (see Fig. 33) and the rear end channel, 2, for the upward extension, 171-2, of the brake lever fulcrum rod, 171. The rear end of the brake lever fulcrum rod is held in place by the rear fulcrum bracket, 172-1, riveted on the outside of the rear belt bracket plate, 156-2.

10 With the improved brake rigging, the forward or brake block fulcrum, is below the brake block, 15 while the rear rolling rod fulcrum extends upward instead of downward, as heretofore; while owing to the position of the rolling side rod, it may be termed a concealed rolling side brake rod.

20 Narrow gauge traction trucks

A number of the older coal mines have gauges as narrow as 3'-0", while in metal ore mines gauges as narrow as 2'-0" are not uncommon.

25 In such cases, the longitudinal supporting side sills may, to advantage, be placed on the outside outside of the car wheels (see Fig. 37) the axle boxings, 60-9, being, say, of the single rigid type, and on the inside of the I-beams, but may 30 be double, drop or swinging axle boxings, the axle, 66, extending through the I-beams and being held in place by the cotter pins, 180.

The wheel hoods, 181, as shown in Fig. 37, designed for side dumping car, are semi-circular, 35 longitudinally, above the axles so as to cover the wheels with reasonable clearance, but with sides vertical below the wheel axle, so as to permit the placing of the wheels in the working position, after which the axle is next placed in position, when the cotter pins are next inserted, the truck being then ready for operation.

40 Transversely, that is, in the direction parallel to the axles, the wheel hoods are preferably, where cradle dump is used, at least approximately rectangular in cross section. The outer vertical faces of the wheel hoods may conveniently rest on the upper flanges of the I-beams, while the inner lower edges of the inner faces of the axle hoods, are preferably also turned horizontally inward, in part so as to give the said 45 lower edges a good bearing on the wheel hood supports, 182, which as shown, are two flat bars of iron, resting on the lower flanges of the I-beams, and as close on either side of the wheels 50 as will permit the ready insertion and removal of the wheels. In case of the cradle dump car, the wheel hood supports may be made say of angle irons, instead of flat bars.

55 The inner vertical faces of the wheel hoods, 50 will evidently make a sort of a bridge truss between said wheel hood supports, and to which the axle hoods, 10-3, may be suitably attached.

Therefore, the longitudinal supporting side sills 60 of the improved traction truck may be either inside or outside the wheels.

Even for the end dump cars, the bottoms, and the deflector plates as well, may also be braced by say T's, (see 183 Fig. 37), parallel to the longitudinal side sills, as these do not involve any appreciable loss of lading space. The wheels, 184, are shown in working position within the wheel casings, 181, being retained the proper gauge outwardly, by means of the loose axle tube (see dotted lines 100-2) the said loose axle tube being

cut the desired length to bear against the inner wheel hubs.

Cradle dump cars

The lower end of the secondary axle belt, 150-6 (Fig. 16) may be extended outward sufficiently to engage an upright belt catch, 180, placed beside the track, just as close as will clear the wheels, so as to hold the car on the cradle dump, while the car is being emptied of its lading, the said outward extension of the secondary axle belt, 150-6, being therefore termed the cradle dump catch.

Preferred construction

A very large percentage of the coal produced in the United States is delivered from the mines in cars that are dumped by tilting the car endwise by means of what is called the horn dump. A small percentage of the coal produced is delivered from the mines in cars that are dumped by turning the car over sideways by means of what is now termed the cradle dump. The preferred construction, therefore, is necessarily based on the end dump type, as the more generally useful construction.

For somewhat similar reason, the preferred construction is also based on that particular type of the improved traction truck which will admit of a few of the cars being added from time to time, as new mine car equipment is needed, to the extensive mine car equipment now in general use throughout the country, the essential feature of which latter may be said to be the placing of the draw-bar over the bumper, which, therefore, may be termed the top draw-bar.

The draw-bars now in common use (practically all top draw-bars) may be classed as either single or double. With the single draw-bar, two clevises, one for either car, connected usually by three links, are used. With the double draw-bar a single link is used to connect the opposite cars. The double draw-bar has been selected for the purpose of illustration, but either may be used as preferred.

The placing of the draw-bar in horizontal line with the vertical center of the bumper, which therefore may be termed the center draw-bar, admits of the simplest possible construction of the improved traction truck and therefore also represents the minimum cost. The top draw-bar, however, in spite of the mechanical complications its use involves, is in a much more convenient position for coupling, and makes the equipment readily interchangeable with practically all equipment now in use.

Again, in much the same way, the cradle dump is theoretically the preferable construction, although owing to the relatively small number of cradle dumps in use, due in part to high cost of the same, the cars will usually be built of the end dump type.

A very large proportion of the draw-bars in use on mine cars are rigidly attached to the cars. The improved traction truck, however, readily admits of spring draft gear, the preferred construction being provided with spring draft gear at one end, and rigid draw-bar at the other end of the car, as economical and yet ample for the general run of mine work.

The improved truck also readily admits of spring bumpers, which, like the spring draft gear, are clearly preferable, for reasons that are too well understood to require statement in detail.

Again, it has not heretofore been found practical, so far as known, to provide mine cars with spring wheel trucks, but the improved traction

truck readily admits of the same, thus placing the improved traction truck generally on an equality with modern railway equipment, while also possessing a number of advantages from a mining 5 standpoint, as herein pointed out.

Haulage strains

What may, for convenience, be termed the tensile haulage strain is that which results from say 10 an electric motor hauling a trip of cars up a steep grade. What may be termed the compressive haulage strain is that which results from the motor holding back a trip of cars on a heavy down grade. The diagonal haulage strains result for 15 instance from the trips of cars passing around curves in the track and may be either compressive or tensile.

What is claimed is:

1. In a low-floor mine or similar rail car for 20 operating in trains, in combination, car wheels and axles, car axle journals, means providing a rigid traction truck frame for supporting the lading load against harmful end-drooping and for transmitting the haulage strains and bumping 25 stresses and for resisting harmful warping or twisting by the overhung lateral lading load whereby the other elements composing the lading body structure of the car may be of relatively light and flimsy construction; the said frame means comprising two stiff metal side sill-means having substantially upright lower wall portions 30 extending substantially straight from end to end of the lading body and located entirely between the upright longitudinal planes of the car wheel flanges and at least in part below the horizontal plane of the axes of the car wheels and comprising also two stiff metal end sill-means 35 perpendicular to the side sill-means and in rigidly secured relationship with the side sill-means at their ends whereby a rectangular frame is 40 formed and each of the said end sill-means having a substantially upright wall, a stationary metal lading bottom structure located at least in part below the said horizontal plane and passing transversely from side sill-means to side sill-means and rigidly attached to both side sill-means in bracing 45 relationship therewith for closing the bottom of the frame means and increasing the rigidity of the said frame means against warping and twisting and whereby a larger lading load may be supported on relatively light lading bottom structures; side lading bottoms extending laterally outside the upright walls of the side sill-means, side and end closure walls separate from the 50 traction truck frame means and extending above the top of the traction truck frame means for completing the lading body, and a bumping and traction structure comprising a substantial transverse cushioning means located outside of and bearing against the upright wall of one of the end sill-means and secured to the end sill-means for absorbing and transmitting bumping stresses to the end sill-means, a metal bumper face engaged with the cushioning means and bodily movable longitudinally of the car as the cushioning means yields under impact, and a coupling structure connected to said one end sill-means and having a member located longitudinally outside of the said upright wall of the one sill-means for receiving a coupling device and connecting the car in train.

3. In a low-floor mine or similar rail car for 40 operating in trains, in combination, car wheels and axles, car axle journals, means providing a rigid traction truck frame for supporting the lading load against harmful end-drooping and for transmitting the haulage strains and bumping 45 stresses and for resisting harmful warping or twisting by the overhung lateral lading load whereby the other elements composing the lading body structure of the car may be of relatively light and flimsy construction; the said frame means comprising two stiff metal side sill-means having substantially upright lower wall portions 50 extending substantially straight from end to end of the lading body and located entirely between the upright longitudinal planes of the car wheel flanges and at least in part below the horizontal 55 plane of the axes of the car wheels and comprising also two stiff metal end sill-means perpendicular to the side sill-means and in rigidly secured relationship with the side sill-means at their ends whereby a rectangular frame is formed and each of the said end sill-means having a substantially upright wall, a stationary metal lading bottom structure located at least in part below the said horizontal plane and passing transversely from side sill-means to side sill-means and from end sill-means to end sill-means 60 in bracing relationship therewith for closing the bottom of the frame means and increasing the rigidity of the said frame means against warping and twisting and whereby a larger lading load may be supported on relatively light lading bottom structures; side lading bottoms extending laterally outside the upright walls of the side sill-means, side and end closure walls separate from the 65 traction truck frame means and extending above the top of the traction truck frame means for completing the lading body, and a bumping and traction structure comprising a substantial transverse cushioning means located outside of and bearing against the upright wall of one of the end sill-means and secured to the end sill-means for absorbing and transmitting bumping stresses to the end sill-means, a metal bumper face engaged with the cushioning means and bodily movable longitudinally of the car as the cushioning means yields under impact, and a coupling structure connected to said one end sill-means and having a member located longitudinally outside of the said upright wall of the one sill-means for receiving a coupling device and connecting the car in train.

2. In a low-floor mine or similar rail car for 70 operating in trains, in combination, car wheels and axles, car axle journals, means providing a rigid traction truck frame for supporting the lading load against harmful end-drooping and for transmitting the haulage strains and bumping 75 stresses and for resisting harmful warping or twisting by the overhung lateral lading load whereby the other elements composing the lading body structure of the car may be of relatively light and flimsy construction; the said frame means comprising two stiff metal side sill-means located between oppositely disposed car wheels

and having substantially upright lower wall portions located at least in part below the horizontal plane of the axes of the car wheels and comprising also two stiff metal end sill-means perpendicular to the side sill-means and in rigidly secured 5 relationship with the side sill-means at their ends whereby a rectangular frame is formed and each of the said end sill-means having a substantially upright wall, a stationary metal lading bottom structure located at least in part below the said horizontal plane and passing transversely from side sill-means to side sill-means and rigidly attached to both side sill-means in bracing relationship therewith for closing the bottom of the frame means and increasing the rigidity of the 10 said frame means against warping and twisting and whereby a larger lading load may be supported on relatively light lading bottom structures; side lading bottoms extending laterally outside the upright walls of the side sill-means, 15 side and end closure walls separate from the traction truck frame means and extending above the top of the traction truck frame means for completing the lading body, and a bumping and traction structure comprising a substantial transverse cushioning means located outside of and bearing against the upright wall of one of the end sill-means and secured to the end sill-means for absorbing and transmitting bumping stresses to the end sill-means, a metal bumper face engaged with the cushioning means and bodily movable longitudinally of the car as the cushioning means yields under impact, and a coupling structure connected to said one end sill-means and having a member located longitudinally outside of the said upright wall of the one sill-means for receiving a coupling device and connecting the car in train.

3. In a low-floor mine or similar rail car for 40 operating in trains, in combination, car wheels and axles, car axle journals, means providing a rigid traction truck frame for supporting the lading load against harmful end-drooping and for transmitting the haulage strains and bumping 45 stresses and for resisting harmful warping or twisting by the overhung lateral lading load whereby the other elements composing the lading body structure of the car may be of relatively light and flimsy construction; the said frame means comprising two stiff metal side sill-means having substantially upright lower wall portions 50 extending substantially straight from end to end of the lading body and located entirely between the upright longitudinal planes of the car wheel flanges and at least in part below the horizontal 55 plane of the axes of the car wheels and comprising also two stiff metal end sill-means perpendicular to the side sill-means and in rigidly secured relationship with the side sill-means at their ends whereby a rectangular frame is formed and each of the said end sill-means having a substantially upright wall, a stationary metal lading bottom structure located at least in part below the said horizontal plane and passing transversely from side sill-means to side sill-means and from end sill-means to end sill-means 60 in bracing relationship therewith for closing the bottom of the frame means and increasing the rigidity of the said frame means against warping and twisting and whereby a larger lading load may be supported on relatively light lading bottom structures; side lading bottoms extending laterally outside the upright walls of the side sill-means, side and end closure walls separate from the 65 traction truck frame means and extending above the top of the traction truck frame means for completing the lading body, and a bumping and traction structure comprising a substantial transverse cushioning means located outside of and bearing against the upright wall of one of the end sill-means and secured to the end sill-means for absorbing and transmitting bumping stresses to the end sill-means, a metal bumper face engaged with the cushioning means and bodily movable longitudinally of the car as the cushioning means yields under impact, and a coupling structure connected to said one end sill-means and having a member located longitudinally outside of the said upright wall of the one sill-means for receiving a coupling device and connecting the car in train.

ing above the top of the traction truck frame means for completing the lading body, and means separate from the elements of the said frame means and connected rigidly with the closure walls for sealing the said traction truck frame means with the end closure walls and side lading walls.

4. In a low-floor mine or similar rail car for operating in trains, in combination, car wheels

10 and axles, car axle journals, means providing a rigid traction truck frame for supporting the lading load against harmful end-drooping and for transmitting the haulage strains and bumping stresses and for resisting harmful warping or

15 twisting by the overhung lateral lading load whereby the other elements composing the lading body structure of the car may be of relatively light and flimsy construction; the said frame means comprising two stiff metal side sill-means

20 having substantially upright lower wall portions extending substantially straight from end to end of the lading body and located entirely between the upright longitudinal planes of the car wheel flanges and at least in part below the horizontal

25 plane of the axes of the car wheels and comprising also two stiff metal end sill-means perpendicular to the side sill-means to overlap in height and having rigidly secured relationship with the side sill-means at their ends whereby a rectangular

30 frame is formed and each of the said end sill-means having a substantially upright wall, a transverse stiffening and bump-cushioning timber located longitudinally outside of and substantially at the height of and engaged with the up-

35 right wall of one said end sill-means for transferring bumping shocks largely toward the side sill-means and relieving the center of the said upright wall, a stationary metal lading bottom structure located at least in part below the said

40 horizontal plane and passing transversely from side sill-means to side sill-means and rigidly attached to both side sill-means in bracing relationship therewith for closing the bottom of the frame means and increasing the rigidity of the

45 said frame means against warping and twisting and whereby a larger lading load may be supported on relatively light lading bottom structures; side lading bottoms extending laterally outside the upright walls of the side sill-means, side

50 and end closure walls separate from the traction truck frame means and extending above the top of the traction truck frame means for completing the lading body, and means separate from the elements of the said frame means and connected rigidly with the closure walls for sealing the said traction truck frame means with the end

55 closure walls and side lading walls.

5. In a mine or similar rail car for operating in trains, the combination of supporting car

60 wheels and axles, means providing a rigid frame for supporting the lading load and transmitting the haulage strains and stresses; the said frame means comprising two oppositely disposed stiff metal longitudinal side sill-means located between

65 oppositely disposed wheels and having upright walls, and a stationary lading bottom structure located at least in part below the horizontal plane of the car wheel axes and extending transversely from one side sill-means to the other and secured

70 in rigid bracing relationship with both said sill-means, and the said frame means also comprising stiff bumping structures at each end of the car; each said bumping structure including means providing a stiff transverse metal struc-

75 ture secured in rigid relationship with the side

sill-means, deep transverse cushioned bumper means for cushioning and transferring the bumping shocks to the said transverse structures and side sill-means, said bumping structure being constructed and arranged for transferring bumping shocks at least in major part to the side sill-means so that the frame means will transmit the haulage strains and stresses independently of the reinforcement of any elements composing other parts of the lading body structure and so that such other parts of the lading body structure may be made of relatively light and flimsy material; side and end closure walls, said walls being in sealed relationship with one another to provide a lading body structure, and a coupling attachment-means connected to each said transverse metal structure and having a coupling member for receiving a coupling device and located in a transverse upright plane cutting the said transverse cushioned bumper means and longitudinally 20 outside of the transverse metal structure.

6. A mine or similar rail car as in claim 5 in which the bumper means includes a transversely extending wood member as a cushion, and including also a sheet metal member extending horizontally and in engagement with one horizontal surface of the wood cushion and fastened thereto for strengthening said wood cushion while it is transferring a bumping shock.

7. In a low-floor mine or similar rail car for 30 operating in trains, in combination, car wheels and axles, car axle journals, means providing a rigid traction truck frame for supporting the lading load against harmful end-drooping and for transmitting the haulage strains and bumping 35 stresses and for resisting harmful warping and twisting by the overhung lateral lading load whereby the other elements composing the lading body structure of the car may be of relatively light and flimsy construction; the said frame

40 means comprising two stiff metal side sill-means having substantially upright lower wall portions located at least in part below the horizontal plane of the car wheel axes, and comprising also two stiff metal end sill-means perpendicular to the side sill-means and in rigidly secured relation-

45 ship with the side sill-means at their ends whereby a rectangular frame is formed, each of the said end sill-means having a substantially upright wall, at least one said side sill-means having

50 an upright wall having a slot therein and in which an axle extends into the slot, the walls of the slot being effective to provide guides for the relative upward and downward movement of the

55 axle and frame whereby the chance of the derailing of the car on an uneven track is lessened, a stationary metal lading bottom structure located at least in part below the said horizontal plane and passing transversely from side sill-means to

60 side sill-means and rigidly attached to both side sill-means for closing the bottom of the frame means and in bracing relationship with the sill-means for increasing the rigidity of the said frame

65 means against warping and twisting so that a larger lading load may be supported on relatively light lading bottom structures; side lading bottoms extending laterally outside the upright walls of the side sill-means, side and end closure walls

70 separate from the traction truck frame means and extending above the top of the traction truck frame means for completing the lading body, and means separate from the elements of the said frame means for sealing the said traction truck

75 frame means and the end closure walls and side lading walls together for receiving the lading.

8. In a low-floor mine or similar rail car for operating in trains, in combination, car wheels and axles, car axle journals, means providing a rigid traction truck frame for supporting the lading load against harmful end-drooping and for transmitting the haulage strains and bumping stresses and for resisting harmful warping and twisting by the overhung lateral lading load whereby the other elements composing the lading body structure of the car may be of relatively light and flimsy construction; the said frame means comprising two stiff metal side sill-means having substantially upright lower wall portions located at least in part below the horizontal plane of the car wheel axes, and comprising also two stiff metal end sill-means perpendicular to the side sill-means and in rigidly secured relationship with the side sill-means at their ends whereby a rectangular frame is formed, each of the said end sill-means having a substantially upright wall, means connecting the truck frame with at least one axle for guided upward and downward relative movement adjacent an end of the axle, so that a car wheel on said axle may remain engaged with the rail on an uneven track, a stationary metal lading bottom structure located at least in part below the said horizontal plane and passing transversely from side sill-means to side sill-means and rigidly attached to both side sill means for closing the bottom of the frame means and in bracing relationship with the sill-means for increasing the rigidity of the said frame means against warping and twisting so that a larger lading load may be supported on relatively light lading bottom structures; side lading bottoms extending laterally outside the upright walls of the side sill-means, side and end closure walls separate from the traction truck frame means and extending above the top of the traction truck frame means for completing the lading body, and means separate from the elements of the said frame means for sealing the said traction truck frame means and the end closure walls and side lading walls together for receiving the lading.
9. In a mine or similar rail car for operating in trains, the combination of supporting car wheels and axles, means providing a rigid frame for supporting the lading load and transmitting the haulage strains and stresses, the said frame means comprising two oppositely disposed stiff metal longitudinal side sill-means having upright walls, a stationary lading bottom structure located at least in part below the horizontal plane of the car wheel axes and extending transversely from one side sill-means to the other and secured in rigid bracing relationship with both said sill-means, and stiff bumping structures at each end of the car, each said bumping structure including means providing a stiff transverse metal structure secured in rigid relationship with the side sill-means for transferring bumping stresses, deep transverse cushioned bumper means for cushioning and transferring the bumping shocks to the said transverse metal structures and side sill-means, said bumping structures being constructed and arranged for transferring bumping shocks at least in major part to the side sill-means so that the frame means will transmit the haulage strains and stresses independently of the reinforcement of any elements composing other parts of the lading body structure and so that such other parts of the lading body structure may be made of relatively light and flimsy

- material, side and end closure walls in sealed relationship with one another and with the bottom to provide a lading body structure, and a coupling attachment-means connected to each said transverse metal structure and having a coupling member for receiving a coupling device and located in a transverse upright plane cutting the said transverse cushioned bumper means and longitudinally outside of the transverse metal structure.
10. In a low-floor mine or similar rail car for operating in trains, in combination, car wheels and axles, car axle journals, means providing a rigid traction truck frame for supporting the lading load against harmful end-drooping and for transmitting the haulage strains and bumping stresses and for resisting harmful warping and twisting by the overhung lateral lading load whereby the other elements composing the lading body structure of the car may be of relatively light and flimsy construction, the said frame means comprising two stiff metal side sill-means having substantially upright lower wall portions located at least in part below the horizontal plane of the axes of the car wheels and comprising also two stiff metal end sill-means perpendicular to the side sill-means and in rigidly secured relationship with the side sill-means at their ends whereby a rectangular frame is formed, each of the said end sill-means having a substantially upright wall, at least one said end sill-means having its upright wall presented as a part of the lading end closure wall at the corresponding end of the car, and the said frame means comprising also a stationary metal lading bottom structure located at least in part below the said horizontal plane and passing transversely from side sill-means to side sill-means for closing the bottom of the frame means and rigidly attached to both side sill-means in bracing relationship therewith for increasing the rigidity of the other portions of the said frame means against warping and twisting so that a larger lading load may be supported on relatively light lading bottom structures, side lading bottoms extending laterally outside the upright walls of the side sill-means, side and end closure walls separate from the traction truck frame means and extending above the top of the traction truck frame means for completing the lading body, one said end closure wall extending to a greater height than the upright wall of the corresponding end sill-means which forms a part of the lading body closure, and means separate from the elements of the said frame means and connected rigidly with the closure walls for sealing the said traction truck frame means and the end closure walls and side lading walls together for receiving the lading.
11. A mine or similar rail car including a rigid structure comprising side sill-means, a floor member and a transversely extending metal member, said structure including vertically spaced metal walls and a connecting wall and providing a recess open toward the end of the car, at least portions of said floor member being located below the horizontal plane of the car wheel axes, bumper cushioning means located in the recess so that the connecting wall thereof forms a rigid backing for the cushioning means, said floor member, cushioning means, and transverse member having mutual overlapping portions in the direction of length of the car with the floor member extending from the transverse member toward the center of length of the car and the

5 cushioning means extending longitudinally beyond the transverse member, said cushioning means being secured to said structure, and bumper-receiving means engaging the end of the said 5 bumper cushioning means.

10 12. A mine or similar rail car having side sills extending from end to end of the lading-receiving portion of the car, a metal lading floor which for at least part of its length provides a lading bottom 10 with the top surface thereof located below the tops of the side sills, a transverse metal means meeting said floor near one end of the car and having at least parts located at a level above adjacent portions of the top of the said floor, 15 bumper cushioning means of wood, the said transverse metal means providing an abutment for said cushioning means, the cushioning means extending longitudinally beyond said transverse metal means, metal top and bottom plates for 20 said wood cushioning means; said floor and transverse metal means being secured to one another and to the side sills to form a rigid structure, at least portions of the side sills and of said transverse metal means being located above the lower- 25 most lading space in the car, and said cushioning means and plates being secured together.

13. In a mine or similar rail car for operating in trains, the combination of supporting car wheels and car axles, a traction structure comprising two longitudinal spaced-apart metal side sill-means extending substantially from end to end of the lading-receiving portion of the car and having substantially upright portions located between oppositely disposed car wheels and the 30 said portions being intersected by the horizontal plane of the axes of the car wheels, side lading closure walls spaced outwardly from the side sill-means, the said traction structure comprising also a sheet metal floor member passing transversely from one of the said side sill-means to the other and rigidly fastened to both said sill-means and bracing them against warping and twisting, the said floor member serving at least in part as a lading bottom and extending longitudinally of the car and located at least in part 35 at a level below the tops of said upright portions of the side sill-means and also at least in part below the said horizontal plane, a transverse metal member located between an end of the car structure and the upright plane of the axes of the adjacent pair of wheels and located at a level above at least parts of the top of the floor member, and a bumper means comprising a cushioning means located between the sill-means and 40 extending beyond the ends of the side sills, said transverse metal member providing an abutment for said cushioning means during bumping.

14. In a mine or similar rail car for operating in trains, the combination of supporting car wheels and car axles, a traction structure comprising two longitudinal, spaced-apart metal side sill-means extending substantially from end to end of the lading-receiving portion of the car and having substantially upright portions located 45 between oppositely disposed car wheels and the said portions being intersected by the horizontal plane of the axes of the car wheels, side lading closure walls spaced outwardly from the side sill-means, the said traction structure comprising also a sheet metal floor member passing transversely from one of the said side sill-means to the other and rigidly fastened to both said sill-means and bracing them against warping and twisting, the said floor member serving 50 at least in part as a lading bottom and extend-

ing longitudinally of the car and located at least in part at a level below the tops of said upright portions of the side sill-means and also at least in part below the said horizontal plane, a transverse metal member located between the end of the car and the upright plane of the adjacent wheel axes and having at least a portion below said horizontal plane, said metal member being located at a level above at least parts of the top of the floor member, and bumper means comprising a cushioning means located between the sill-means and extending beyond the ends of the side sills, said transverse metal member providing an abutment for said cushioning means during bumping.

15. In a mine or similar rail car for operating in trains, the combination of supporting car wheels and axles, two oppositely disposed stiff metal longitudinal side sill-means having upright walls and a stationary lading bottom structure 20 located at least in part below the horizontal plane of axes of the car wheels and extending transversely from one side sill-means to the other and secured in rigid bracing relationship with both said sill-means, and stiff bumping structures at 25 each end of the car; each said bumping structure including means providing stiff transverse metal structures secured in rigid relationship with the side sill-means, heavy wood timbers for cushioning and transferring the bumping shocks, and metal 30 bumping plates having substantially upright faces and engaged with said timbers, said bumping structure being constructed and arranged for transferring bumping shocks at least in major part to the side sill-means so that the bumping 35 strains and stresses will be transmitted independently of the reinforcement of any elements composing other parts of the lading body structure and so that such other parts of the lading body structure may be made of relatively light and 40 flimsy material; wing lading bottoms extending laterally outside the upright walls of the side sill-means, said wing bottoms being located at least in substantial part below said horizontal plane so that a large low-hung lading capacity is obtained outside said upright walls in a low car, 45 side and end closure walls in sealed relationship with one another and the wing bottoms to complete the lading body structure, and a coupling 50 attachment-means connected to said transverse metal-means and having a coupling member located longitudinally outside of the transverse metal-means and in a transverse upright plane cutting the said wood timbers for receiving a 55 coupling device.

16. In a mine or similar rail car for operating in trains, the combination of supporting car wheels and axles, two oppositely disposed stiff metal longitudinal side sill-means having upright walls located between wheels at opposite sides of 60 the car, axle boxings on the side sill-means and located between the wheels for engaging the corresponding axles, a stationary lading bottom structure located at least in part below the horizontal plane of axes of the car wheels and extending transversely from one side sill-means to the other and secured in rigid bracing relationship with both said sill-means, and stiff bumping structures at each end of the car; each said bumping structure including means providing stiff 65 transverse metal structures secured in rigid relationship with the side sill-means, heavy wood timbers for cushioning and transferring the bumping shocks, and metal bumping plates having substantially upright faces and engaged with 70

said timbers, said bumping structure being constructed and arranged for transferring bumping shocks at least in major part to the side sill-means so that the bumping strains and stresses will be transmitted independently of the reinforcement of any elements composing other parts of the lading body structure and so that such other parts of the lading body structure may be made of relatively light and filmsy material; wing lading bottoms extending laterally outside the upright walls of the side sill-means, said wing bottoms being located at least in substantial part below said horizontal plane so that a large low-hung lading capacity is obtained outside said upright walls in a low car, side and end closure walls in sealed relationship with one another and the wing bottoms to complete the lading body structure, and a coupling attachment-means connected to said transverse metal-means and having a coupling member located longitudinally outside of the transverse metal-means and in a transverse upright plane cutting the said wood timbers for receiving a coupling device.

17. In a mine or similar rail car for operating in trains, the combination of supporting car wheels and axles, two oppositely disposed stiff metal longitudinal side sill-means having upright walls, a stationary lading bottom structure located at least in part below the horizontal plane of axes of the car wheels and extending transversely from one side sill-means to the other and secured in rigid bracing relationship with both said sill-means, and stiff bumping structures at each end of the car; each said bumping structure including means providing stiff transverse metal structures secured in rigid relationship with the side sill-means, heavy wood timbers for cushioning and transferring the bumping shocks, and metal bumping plates having substantially upright faces and engaged with said timbers, said bumping structure being constructed and arranged for transferring bumping shocks at least in major part to the side sill-means so that the bumping strains and stresses will be transmitted independently of the reinforcement of any elements composing other parts of the lading body structure and so that such other parts of the lading body structure may be made of relatively light and filmsy material; wing lading bottoms extending laterally outside the upright walls of the side sill-means, said wing bottoms being located at least in substantial part below said horizontal plane so that a large low-hung lading capacity is obtained outside said upright walls in a low car, side and end closure walls in sealed relationship with one another and the wing bottoms to complete the lading body structure, and portions of the wing lading bottoms located between an end of the car and the upright transverse plane of the wheels adjacent the said end being positioned substantially at the level of the said lading bottom structure so that the upright transverse section provided by the side closure walls and said wing bottoms and bottom structure is substantially rectangular.

18. In a mine or similar rail car for operating in trains, the combination of supporting car wheels and axles, two oppositely disposed stiff metal longitudinal side sill-means having upright walls located between wheels at opposite sides of the car, axle boxings on the side sill-means and located between the wheels for engaging the corresponding axles, a stationary lading bottom structure located at least in part below the horizontal plane of axes of the car wheels and extend-

ing transversely from one side sill-means to the other and secured in rigid bracing relationship with both said sill-means, and stiff bumping structures at each end of the car; each said bumping structure including means providing stiff transverse metal structures secured in rigid relationship with the side sill-means, heavy wood timbers for cushioning and transferring the bumping shocks, and metal bumping plates having substantially upright faces and engaged with said timbers, said bumping structure being constructed and arranged for transferring bumping shocks at least in major part to the side sill-means so that the frame means will transmit the bumping strains and stresses independently of the reinforcement of any elements composing other parts of the lading body structure and so that such other parts of the lading body structure may be made of relatively light and filmsy material; wing lading bottoms extending laterally outside the upright walls of the side sill-means, said wing bottoms being located at least in substantial part below said horizontal plane so that a large low-hung lading capacity is obtained outside said upright walls in a low car, and portions of the wing lading bottoms located between an end of the car and the upright transverse plane of the wheels adjacent the said end being positioned substantially at the level of the said lading bottom structure so that the upright transverse section provided by the side closure walls and said wing bottoms and bottom structure is substantially rectangular.

19. In a mine or similar rail car for operating in trains, the combination of supporting car wheels and axles, means providing a rigid frame for supporting the lading load and transmitting the haulage strains and stresses; the said frame means comprising two oppositely disposed stiff metal longitudinal side sill-means having upright walls and a stationary lading bottom structure located at least in part below the horizontal plane of the car wheel axes and extending transversely from one side sill-means to the other and secured in rigid bracing relationship with both said sill-means, and the said frame means also comprising stiff bumping structures at each end of the car; each said bumping structure including means providing stiff transverse metal structures secured in rigid relationship with the side sill-means, heavy transverse members provided with cushioning means for cushioning and transferring the bumping shocks to the said transverse structures and side sill-means, and metal bumping plates having substantially upright faces and engaged with said transverse members, said bumping structure being constructed and arranged for transferring bumping shocks at least in major part to the side sill-means so that the frame means will transmit the bumping strains and stresses independently of the reinforcement of any elements composing other parts of the lading body structure and so that such other parts of the lading body structure may be made of relatively light and filmsy material; side and end closure walls, said walls being in sealed relationship with one another to provide a lading body structure, wing lading bottoms extending laterally outward from the side sill-means each in a substantially horizontal direction and each having at least a portion located at the level of the lading bottom structure and so that the said wing bottoms and bottom structure provide with the side closure walls a lading body of substantially rectangular section in an upright transverse plane

- between the corresponding end of the car and the wheels adjacent thereto whereby a relatively large overhung lading capacity is obtained in a relatively low car, and a coupling attachment-means connected to said transverse metal-means and having a coupling member located in a transverse upright plane cutting the said wood timbers and longitudinally outside of the transverse metal-means for receiving a coupling device.
20. In a mine or similar rail car for operating in trains, the combination of supporting car wheels and axles, means providing a rigid frame for supporting the lading load and transmitting the haulage strains and stresses; the said frame means comprising two oppositely disposed stiff metal longitudinal side sill-means having upright walls located between oppositely disposed wheels and a stationary lading bottom structure located at least in part below the horizontal plane of the car wheel axes and extending transversely from one side sill-means to the other and secured in rigid bracing relationship with both said sill-means, and the said frame means also comprising stiff bumping structures at each end of the car; each said bumping structure including means providing stiff transverse metal structures secured in rigid relationship with the side sill-means, heavy transverse members provided with cushioning means for cushioning and transferring the bumping shocks to the said transverse structures and side sill-means, and metal bumping plates having substantially upright faces and engaged with said transverse members, said bumping structure being constructed and arranged for transferring bumping shocks at least in major part to the side sill-means so that the frame means will transmit the bumping strains and stresses independently of the reinforcement of any elements composing other parts of the lading body structure and so that such other parts of the lading body structure may be made of relatively light and flimsy material; side and end closure walls, said walls being in sealed relationship with one another to provide a lading body structure, wing lading bottoms extending laterally outward from the side sill-means each in a substantially horizontal direction and each having at least a portion located at the level of the lading bottom structure and so that the said wing bottoms and bottom structure provide with the side closure walls a lading body of substantially rectangular section in an upright transverse plane between the corresponding end of the car and the wheels adjacent thereto whereby a relatively large overhung lading capacity is obtained in a relatively low car, and a coupling attachment-means connected to said transverse metal-means and having a coupling member located in a transverse upright plane cutting the said wood timbers and longitudinally outside of the transverse metal-means for receiving a coupling device.
21. In a low-floor mine or similar rail car for operating in trains, in combination, car wheels and axles, car axle journals, means providing a rigid traction truck frame for supporting the lading load against harmful end-drooping and for transmitting the haulage strains and bumping stresses and for resisting harmful warping or twisting by the overhung lateral lading load whereby the other elements composing the lading body structure of the car may be of relatively light and flimsy construction; the said frame means comprising two stiff metal side sill-means located between oppositely disposed car wheels and having substantially upright lower wall portions located at least in part below the horizontal plane of the axes of the car wheels and comprising also two stiff metal end sill-means perpendicular to the side sill-means and in rigidly secured relationship with the side sill-means at their ends whereby a rectangular frame is formed and each of the said end sill-means having a substantially upright wall, a stationary metal lading bottom structure located at least in part below the said horizontal plane and passing transversely from side sill-means to side sill-means and rigidly attached to both side sill-means in bracing relationship therewith for closing the bottom of the frame means and increasing the rigidity of the said frame means against warping and twisting and whereby a larger lading load may be supported on relatively light lading bottom structures; side wing lading bottoms extending laterally outside the upright walls of the side sill-means, side and end closure walls separate from the traction truck frame means and extending above the top of the traction truck frame means for completing the lading body, said wing bottoms having portions substantially horizontal at the level of the adjacent portion of lading bottom structure, said wing bottom portions and lading bottom structure portion being located entirely below the said horizontal plane so that the transverse upright cross-section of the lading body thereat is substantially rectangular whereby a relatively large overhung lading capacity is obtained in a relatively low car, and means separate from the elements of the said frame means for sealing the said traction truck frame means with the end closure walls and side lading walls.
22. In a mine or similar rail car for operating in trains, the combination of supporting car wheels and axles, means providing a rigid frame for supporting the lading load and transmitting the haulage strains and stresses; the said frame means comprising two oppositely disposed stiff metal longitudinal side sill-means having upright walls located laterally outside oppositely disposed wheels and a stationary lading bottom structure located at least in part below the horizontal plane of the car wheel axes and extending transversely from one side sill-means to the other and secured in rigid bracing relationship with both said sill-means, and the said frame means also comprising stiff bumping structures at each end of the car; each said bumping structure including means providing stiff transverse metal structures secured in rigid relationship with the side sill-means, heavy wood timbers for cushioning and transferring the bumping shocks to the said transverse structures and side sill-means and metal bumping plates having substantially upright faces and engaged with said timbers, said bumping structure being constructed and arranged for transferring bumping shocks at least in major part to the side sill-means so that the frame means will transmit the bumping strains and stresses independently of the reinforcement of any elements composing other parts of the lading body structure and so that such other parts of the lading body structure may be made of relatively light and flimsy material; side and end closure walls, said walls being in sealed relationship with one another to provide a lading body structure, wing lading bottoms extending laterally outward from the side sill-means each in a substantially horizontal direction and each having at least a portion located at the level of the lading bottom structure and so that the

5 said wing bottoms and bottom structure provide with the side closure walls a lading body of substantially rectangular section in an upright transverse plane between the corresponding end of the car and the wheels adjacent thereto whereby a 10 relatively large overhung lading capacity is obtained in a relatively low car, and a coupling attachment-means connected to said transverse metal-means and having a coupling member located in a transverse upright plane cutting the said wood timbers and longitudinally outside of the transverse metal-means for receiving a coupling device.

15 23. In mine or similar rail cars, the combination of a lading body structure having side and end closure wall-structures, at least two stiff metal side sill-means with substantially upright wall portions, the said sill-means passing longitudinally substantially from end to end of the 20 lading body to support the lading load against end-drooping, car wheels having axes in a horizontal plane cutting the vertical planes of the said upright wall portions above the lower edges of said wall portions, a wing lading bottom laterally outside of one said upright wall portion and located low in respect of the said one wall portion whereby a lading body of relatively large overhung capacity is obtained in a relatively low car and whereby lading space is provided outside the 25 said wall portions in the horizontal planes of the said axes and of at least portions of the said wall portions, and a central lading bottom structure extending transversely between oppositely disposed sill-means and rigidly fastened to the said 30 sill-means and bracing them against warping and twisting.

35 24. In mine or similar rail cars, the combination of a lading body structure having side and end closure wall-structures, at least two stiff metal side sill-means with substantially upright 40 wall portions located between the wheels at opposite sides of the car, the said sill-means passing longitudinally substantially from end to end of the lading body to support the lading load against end-drooping, car wheels having axes in a horizontal 45 plane cutting the vertical planes of the said upright wall portions above the lower edges of said wall portions, a wing lading bottom laterally outside of one said upright wall portion and located low in respect of the said one wall portion whereby a lading body of relatively large overhung capacity is obtained in a relatively low car and whereby lading space is provided outside the 50 said wall portions in the horizontal planes of the said axes and of at least portions of the said wall portions, and a central lading bottom structure extending transversely between oppositely disposed 55 sill-means and rigidly fastened to the said sill-means and bracing them against warping and twisting.

60 25. In mine or similar rail cars, the combination of a lading body structure having side and end closure wall-structures, car wheels and axles, at least two stiff metal side sill-means with substantially upright wall portions, the said sill-means passing longitudinally substantially from end to end of the lading body to support the lading load against end-drooping, car wheels having axes in a horizontal plane cutting the vertical 65 planes of said upright wall portions above the lower edges of said wall portions, a wing lading bottom laterally outside of one said upright wall portion and located low in respect of the said one wall portion whereby a lading body of relatively large overhung capacity is obtained in a rela-

tively low car and whereby lading space is provided outside the said wall portions in the horizontal planes of the said axes and of at least portions of the said wall portions, and a central lading bottom structure extending transversely 5 between oppositely disposed sill-means and rigidly fastened to the said sill-means and bracing them against warping and twisting, said central lading bottom structure being located substantially at the level of said wing lading bottom so 10 that the side closure wall structures form therewith a transverse upright section of substantially rectangular form between two oppositely disposed wheels and the rearward end closure wall, whereby parts of the lading contacting said 15 lading bottom and lading bottom structure at said transverse upright section are located entirely below the horizontal plane of the axes of the car wheels.

20 26. In mine or similar rail cars, the combination of car wheels, car axles, side and end closure walls, sub-axle lading bottom portions located both outside and inside the upright longitudinal planes of the flanges of the car wheels, stiff flanged metal side beams securely fastened to adjacent portions of the bottoms and extending longitudinally substantially from end to end of the lading body whereby the lading load is supported without harmful end-drooping, and the said beams being located between oppositely disposed 25 side closure walls and being located also at least in substantial part above the said lading bottom portions so that the said beams extend upward above the said plane into the lading body space and whereby lading space is afforded at each side 30 of each beam below the tops of the said beams and whereby a relatively large lading capacity is obtained in a relatively low but stiff car of relatively light construction, said bottom portions being secured to the beams for bracing the beams 35 against warping and twisting.

40 27. In mine or similar rail cars, the combination of a lading body-structure, car wheels, means providing a rigid rectangular traction truck frame for supporting the lading load without harmful end-drooping and for taking the haulage strains and stresses, the said frame means being composed of flanged metal side sills with upright lower walls located at least in part below the horizontal plane of the axes of the car 45 wheels, and being composed also of end sill-structures each having at least one flanged metal sill-member perpendicular to the side sills and extending from one side sill to the other and rigidly secured to both sills, a lading bottom means extending transversely from side sill to side sill and rigidly secured to the side sills whereby the 50 said sills are braced against warping and twisting, side closure walls for the lading body-structure spaced from the side sills, means for sealing the 55 elements composing the said frame means with the adjacent elements of the lading body-structure, and the said lading bottom means being located sub-axle and also located low in reference to elements of the frame-means whereby a 60 relatively large and low central lading body capacity is obtained, at least portions of the side sills and of at least one end sill-structure being located above the lowermost lading space in the car.

65 28. In mine or similar rail cars, the combination of car axles, a lading body, relatively flimsy side closure wall means, two stiff load-supporting flanged metal side-beams longitudinal of the lading body whereby the lading load is supported 70

by these metal beams without harmful end-drooping, thin metal lading bottoms having portions lying laterally both outside and inside each of the said side-beams and at least one of the 5 said portions lying below the horizontal plane of the journals of the car axles and also below the horizontal plane of the top of the adjacent said beam and another said portion on the other side of the adjacent said beam lying at least 10 below the horizontal plane of the top of said beam whereby a relatively large lading capacity is obtained in a relatively low car, and with relatively thin and light lading bottoms and relatively flimsy side closure wall means, and axle 15 supports located between oppositely disposed wheels and attached in supporting relationship to the car structure.

29. In a low-floor mine or similar rail car for operating in trains, in combination, car wheels 20 and axles, car axle journals, means providing a rigid traction truck frame for supporting the lading load against harmful end-drooping and for transmitting the haulage strains and bumping stresses and for resisting harmful warping 25 or twisting by the overhung lateral lading load whereby the other elements composing the lading body structure of the car may be of relatively light and flimsy construction; the said frame means comprising two stiff metal side sill-means 30 extending substantially straight from end to end of the lading body and having substantially upright lower wall portions located at least in part below the horizontal plane of the axes of the car wheels and comprising also two stiff metal end 35 sill-means perpendicular to the side sill-means and in rigidly secured relationship with the side sill-means at their ends whereby a rectangular frame is formed and each of the said end sill-means having a substantially upright wall, a 40 stationary metal lading bottom structure located at least in part below the said horizontal plane and passing transversely from side sill-means to side sill-means and rigidly attached to both side sill-means in bracing relationship therewith for 45 closing the bottom of the frame means and increasing the rigidity of the said frame means against warping and twisting and whereby a larger lading load may be supported on relatively light lading bottom structure; side lading 50 bottoms extending laterally outside the upright walls of the side sill-means at a lesser angle than the angle of repose of loose coal and similar lading, side and end closure walls separate from the traction truck frame means and extending 55 above the top of the traction truck frame means for completing the lading body, and means separate from the elements of the said frame means connected rigidly with the closure walls for sealing the said traction truck frame means with the 60 end closure walls and side lading walls.

30. In a mine or similar rail car, the combination of car wheels, car axles with journals, a central lading body portion extending longitudinally of the car including longitudinal load-supporting and bracing means lying between oppositely disposed wheels, side lading wing-body portions extending longitudinally of the car and each wing-body having wing lading bottoms whose top surfaces directly rearward longitudinally of the most rearward adjacent wheel lie below the horizontal plane of the top of the said wheel, supporting means for the car axles located outside oppositely disposed car wheels, stiff longitudinally extending load-transferring 70 means to which the said supporting means are

rigidly attached and the said extending means being themselves rigidly attached to the structures of the wing bodies, side and end upright closure wall-structures of relatively flimsy construction, and a stationary metal sub-axle lading 5 bottom rigidly attached to the said load-supporting means.

31. In a mine or similar rail car, the combination of car wheels and axles with journals; supporting means for the car axles located outside the 10 wheels, stiff longitudinally extending load-transferring means including elements located outside the wheels and connected to said supporting means and an element located between the wheels, lading body structures extending longitudinally of 15 the car including a metal sub-axle lading bottom and also including wing lading bottoms whose top surfaces longitudinally rearward of the adjacent wheel lie below the horizontal plane of the top of the said wheel, said structures also including side and end upright closure-wall means of relatively flimsy construction, said bottoms being rigidly secured to said longitudinally extending means for bracing the same and being supported thereby against end drooping. 25

32. In a mine or similar rail car, the combination of a lading body structure with side and end closure walls, car wheels and axles, a sub-axle lading bottom, longitudinal flanged metal side-beams located between the opposite side walls 30 and spaced from the upright planes through the top portions of the said side closure walls and sufficiently stiff to support the lading load without harmful end-drooping and having upright lower wall portions located below the horizontal 35 plane of the axes of the car wheels, sealing means as separate elements between the said side beams and adjacent parts of the lading body structure, and axle boxings guided from said side beams and movable up and down in respect thereto 40 whereby the chance of the car being derailed on an uneven track is lessened.

33. In a mine or similar rail car, the combination of a lading body structure with side and end closure walls, car wheels and axles, a sub-axle 45 lading bottom, longitudinal flanged metal side-beams located between the car wheels and sufficiently stiff to support the lading load without harmful end-drooping and having upright lower wall portions located below the horizontal plane 50 of the axes of the car wheels, sealing means as separate elements between the said side beams and adjacent parts of the lading body structure, and axle boxings guided from said side beams and movable up and down in respect thereto 55 whereby the chance of the car being derailed on an uneven track is lessened.

34. In a mine or similar rail car, the combination of car wheels and axles, at least one axle having two wheels thereon, longitudinal load-supporting sill means extending substantially from end to end of the lading-receiving portion of the car, end bumper structures, a substantially horizontal secured central lading bottom of substantially rectangular perimeter and extending from 65 one bumping structure to the other and located between the two car wheels on said one axle, a wing lading bottom having its top surface extending substantially from the horizontal plane of the top surface of the central lading bottom 70 laterally outward from the upright plane of the inside of the flange of the car wheel on the same side of the car in a plane cutting the said wheel, said central wing lading bottoms having their adjacent edges substantially at the same horizon- 75

- tal plane, the adjacent sill means extending upwardly above said plane so that lading space is provided at both sides of said adjacent sill means, side closure walls having upright portions located laterally outside of the sill means, an upwardly extending section covering the said wheel and closing said aperture, and other laterally extending stiffening means for supporting said wing bottom.
- 10 35. In a mine or similar rail car, the combination of car wheels and axles, at least one axle having two wheels thereon, longitudinal load-supporting sill means extending substantially from end to end of the lading-receiving portion of the car, end bumper structures, a substantially horizontal secured central lading bottom of substantially rectangular perimeter and extending from one bumper structure to the other and located between the two car wheels on said one axle, a 15 wing lading bottom having its top surface extending substantially from the horizontal plane of the top surface of the central lading bottom laterally outward from the upright plane of the inside of the flange of the car wheel on the same side of the car in a plane cutting the said wheel, said central wing lading bottoms having their adjacent edges substantially at the same horizontal plane, the adjacent sill means extending upwardly above said plane so that lading space is provided 20 at both sides of said adjacent sill means, side closure walls having upright portions located laterally outside of the sill means, wheel hood-means over the wheels and closing said aperture with portions serving as means for supporting the lading bottoms, and other metal means extending laterally outwardly and transversely beyond the 25 said upright plane adjacent the centers and ends of the car whereby the lading wing bottoms receive additional support.
- 40 36. In a mine or similar rail car, the combination of car wheels and axles, end bumper structures, a substantially horizontal secured metal central lading bottom means of substantially rectangular perimeter and extending from one end bumper structure to the other and located between wheels at opposite sides of the car and located at least in substantial part below the horizontal plane of the wheel axes, a wing lading bottom extending substantially from the level of 45 such low part of the central lading bottom laterally outward through the upright plane of the inside of the flange of a car wheel on the same side of the car in a plane cutting the said wheel and wheel hood-means over the wheels with portions serving as means for supporting the lading 50 wing-bottoms, and other metal means extending laterally outwardly and transversely beyond the said upright plane adjacent the center and ends of the car whereby the lading wing-bottoms receive additional support.
- 55 37. In a mine or similar rail car, the combination of car wheels and axles, end structures including metal bumpers and coupling means, a lading body including a substantially horizontal 60 central secured sub-axle lading bottom of rectangular perimeter extending from end to end of the lading body and located between the longitudinal upright planes of the inside of the flanges of laterally oppositely disposed wheels, wing bottoms having their inner lading-receiving portions located at a higher level than the lowest portions of said central bottom and extending from substantially the upright planes of the edges of the central lading bottom laterally outward through 70 the said upright planes of the inside of the flanges

of the car wheels on the same side of the car in planes intersecting the said wheels, upwardly extending coverings over the said wheels of wide lateral dimensions whereby the wheels may be readily removed from the axles, and laterally outward extending stiffening members for supporting 5 the wing bottoms.

38. In mine or similar rail cars for operating in trains, the combination of a lading body having side closure wall structures having substantially upright outside portions, two side sills with substantially upright lower portions and the said sills passing substantially from end to end of the lading body and of sufficient stiffness to endure the haulage strains and stresses and to support the 10 lading load against end drooping, and the upright planes of the lower portions of the side sills being laterally inside the upright outside portions of the side closure walls, car wheels having axes in a horizontal plane cutting the side closure walls, a central longitudinal section of lading bottom 15 rigidly secured to a lower portion of each of the two side sills, a wing lading body laterally outside a lower portion of each of the side sills, and metal wing lading-bottoms for each of the wing lading bodies which constitute elements separate 20 from the central lading bottom, and the said wing-bottoms being fastened to the lower portions of the side sills and being sealed to the side sills at points which at least to some extent are 25 below the horizontal plane of the axes of the car wheels whereby the said lower portions of the side sills project into the lading body of the car above the level of parts of the adjacent lading bottoms, and whereby the level of the wing bottoms at the 30 side sills need not necessarily correspond with the level of the adjacent central lading bottom section whereby the building of the car is simplified by the use of smaller and separate sections of lading bottom and whereby the shape of the lading 35 wing-bottoms may be more readily varied. 40

39. In mine or similar rail cars for operating in trains, the combination of a lading body having side closure wall structures having substantially upright outside portions, two side sills with substantially upright lower portions and the said sills passing substantially from end to end of the lading body and of sufficient stiffness to endure the haulage strains and stresses and to support the lading load against end drooping, and the upright planes of the lower portions of the side sills being laterally inside the upright outside portions of the side closure walls, car wheels having axes in a horizontal plane cutting the side closure walls, a central longitudinal section of lading bottom 45 rigidly secured to a lower portion of each of the two side sills, a wing lading body laterally outside a lower portion of each of the side sills, and metal wing lading-bottoms for the wing lading bodies which constitute elements separate 50 from the central lading bottom, and whereby the level of the wing bottoms at the side sills need not necessarily correspond with the level of the adjacent central lading bottom section whereby the building of the car is simplified by the use of smaller and separate sections of lading bottom 55 and whereby the shape of the lading wing-bottoms may be more readily varied. 60

40. In a mine or similar rail car, the combination of car wheels and axles having journals, a lading body structure with oppositely disposed side closure walls, a sub-axle lading bottom 65 means, and at least two stiff flanged metal beam-members having upright wall-portions and supporting the lading body structure against harm- 70 75

- ful end-drooping and the said beam-members lying at least in substantial part above the lading bottom means and lying between oppositely disposed side closure walls so that the said beam-members project into at least one transverse upright section of the lading body whereby there is lading space in that upright section on both sides of portions of the upright walls of each of the said beam-members and in the horizontal plane of the said walls whereby a bottom low in respect of the beam-members is obtained and whereby a relatively large lading capacity is obtained in a relatively low car body-structure.
41. In a four-wheel mine or similar rail car, the combination of a lading body having end and side closure wall structures and a lading bottom structure, car wheels, said bottom structure including a central metal lading bottom means extending longitudinally between oppositely disposed car wheels substantially to the ends of the lading body and made up at least in part of sections transverse to the length of the lading body, and at least substantial portions of the top surface of the said bottom means lying below the horizontal plane of the axes of the car wheels, two car axles each supporting oppositely disposed wheels, flanged metal side sills lying between oppositely disposed wheels and having upright web-sections which are cut by the said horizontal plane, and the said side sills extending longitudinally substantially from end to end of the lading body and of sufficient rigidity as beams to support the lading load against end drooping, car axle support bearings rigidly attached to the side sills and at least in part located between oppositely disposed sills whereby the sills may be located close to the wheels for providing a relatively wide central lading space, and axle coverings extending over said car axles and over at least parts of the said axle support bearings and the said axle coverings being in rigid relation with the said upright web-sections of the side sills whereby the said sills are braced against sidewise movement in respect of the adjacent car wheels.
42. In a four-wheel mine or similar rail car, the combination of a lading body having end and side closure wall structures and a lading bottom structure, car wheels, said bottom structure including a central metal lading bottom means extending longitudinally between oppositely disposed car wheels substantially to the ends of the lading body, and at least substantial portions of the top surface of the said bottom means lying below the horizontal plane of the axes of the car wheels, two car axles each supporting oppositely disposed wheels, flanged metal side sills lying between oppositely disposed wheels and having upright web-sections which are cut by the said horizontal plane, and the said side sills extending longitudinally substantially from end to end of the lading body and of sufficient rigidity as beams to support the lading load against end drooping, car axle support bearings rigidly attached to the side sills and at least in part located between oppositely disposed sills whereby the sills may be located close to the wheels for providing a relatively wide central lading space, and axle coverings extending over said car axles and over at least parts of the said axle support bearings and the said axle coverings being in rigid relation with the said upright web-sections of the side sills whereby the said sills are braced against sidewise movement in respect of the adjacent car wheels.
43. In mine or similar rail cars for operating in trains, the combination of car wheels, a lading body structure having side and end closure walls and a lading bottom structure, a central lading bottom section extending longitudinally between oppositely disposed car wheels, a rigid traction truck frame means having stiff flanged metal side beams with upright lower portions and the said side beams reaching substantially to the end closure walls and the said frame means having stiff bump-resisting end sill-structures, each comprising a stiff metal end-sill member with an upright wall perpendicular to the side beams and rigidly attached to the ends of the side beams whereby the said frame means has a rectangular inner perimeter and whereby the said frame means is sufficiently rigid to take the strains and stresses of the haulage and to support the lading load against end-drooping, deep transverse-cushioned bumper means beyond the upright wall of at least one metal end-sill member and secured to the said end-sill member, upright metal bumper faces on the bumper means with metal parts extending horizontally toward the metal end-sill member, lading wing-bottoms at least portions of which extend laterally outward from the upright planes of the lower portions of the side beams past the adjacent car wheels below the tops thereof and include deep hood-form means over the tops of the car wheels that project above the planes of the wing-bottoms, and sealing means associating the parts of the lading body structure, whereby a car with low-hung wing-bottoms and of relatively large capacity is obtained in a relatively low car.
44. In a mine or similar rail car for operating in trains, the combination of a lading body structure having side and end closure walls and a lading bottom structure, car wheels, at least two car axles, a central lading bottom portion between the sills lying at least in substantial part below the horizontal plane of the axes of the car wheels, metal side sills having upright walls lying between oppositely disposed car wheels and at least portions of the said walls lying below the said horizontal plane, lading wing-bodies laterally outside the upright walls of the adjacent side sills and the said wing-bodies having lading wing bottoms with at least portions lying in planes cutting the adjacent car wheels, means secured to the side sills by which the axles support the side sills and at least a substantial portion of one of the said axle-supporting means being located between oppositely disposed side sills whereby a larger lading capacity may be obtained at a low level between oppositely disposed sills.
45. In a mine or similar rail car for operating in trains, the combination of a lading body structure having side and end closure walls and a lading bottom structure, car wheels, at least two car axles, a central lading bottom portion between the sills lying at least in substantial part below the horizontal plane of the axes of the car wheels, metal side sills having upright walls lying between oppositely disposed car wheels and at least portions of the said walls lying below the said horizontal plane, lading wing-bodies laterally outside the upright walls of the adjacent side sills and the said wing-bodies having lading wing bottoms with at least portions lying in planes cutting the adjacent car wheels, means secured to the side sills by which the axles support the side sills and at least a substantial portion of one of the said axle-supporting means

- being located between said upright walls of oppositely disposed side sills whereby a larger lading capacity may be obtained at a low level between oppositely disposed sills, said sill-supporting means including devices for affording the axles a limited relative upward and downward movement in respect of the side sills and for guiding the same during such movement, whereby danger of derailment on an uneven track is lessened.
46. In a mine or similar rail car for operating in trains, the combination of a lading body structure having side and end closure walls and a lading bottom structure, the side closure walls having substantially upright portions at the top of the car, car wheels, at least two car axles, a central longitudinally extending stationary sub-axle lading bottom section, stiff flanged metal side sills as separate elements extending longitudinally and having upright lower walls lying between the upright planes of the upright portions of oppositely disposed side closure walls and the said lower walls being located at least in part below the horizontal plane of the axes of the car wheels, lading wing-bodies laterally outside the lower walls of the adjacent side sills and the said wing-bodies having wing-bottoms with at least portions lying in planes cutting the adjacent car wheels, and support-means for the car axles and secured to the side sills and at least substantial portions of one of the said support-means being located between the upright lower walls of oppositely disposed side sills.
47. In mine or similar rail cars, the combination of a lading body having side and end closure walls and a lading bottom structure, car wheels, car axles, stiff flanged metal load-supporting side sills having upright lower walls located at least in part below the horizontal plane of the axes of the car wheels and extending longitudinally from end to end of the lading body whereby the lading body is supported by the said side sills from harmful end-drooping, bumper structures at the ends of the car, one of said bumper structures including a member extending transversely from side sill to side sill and connected thereto, said member having portions extending above and below said horizontal plane, the lading bottom structure including substantially rectangular sections extending in horizontal planes from side sill to side sill at least in substantial part below the said horizontal plane and rigidly attached to the side sills substantially at their bottoms and bracing the said sills against warping and twisting, one said section being secured to said bumper structure member for bracing the same relative to said sills, and two of the said rectangular sections having transverse edges separated near one of the said axles whereby the said edges lie on opposite sides of the said axle, and an axle housing sealing the two separated sections.
48. In mine or similar rail cars, the combination of a lading body, car wheels, car axles, flanged metal longitudinal side sill-means which are located between opposite wheels and are of themselves sufficiently stiff to support the lading body without harmful end-drooping, and the said sill-means having upright portions located at least in part below the horizontal plane of the axes of the car wheels, a sub-axle lading bottom and axle boxings having upright longitudinal walls located at least in part in the lading space and inside the upright walls of oppositely disposed side sill-means and rigidly secured thereto.
49. In mine or similar rail cars, the combination of a lading body, car axles, and wheels including means for limiting the lateral movements of a wheel in respect of its axle, said body including upright side closure walls, flanged metal longitudinal side sill-means located laterally outside the wheels and inside of and spaced from the side closure walls and being sufficiently stiff as separate elements to support the lading body without harmful end-drooping, the said sill-means having upright portions located at least in part below the horizontal plane of the axes of the car wheels, a sub-axle lading bottom, and axle boxings having upright longitudinal walls inside the upright walls of oppositely disposed side sill-means and rigidly secured thereto and including hub portions projecting inwardly from the upright longitudinal walls of the axle boxings and engageable for restraining the lateral movement of the car axles in respect of the said sill-means.
50. In a mine or similar rail car, the combination of car axle journals, car wheels, side and end closure walls, straight longitudinal load-supporting sills located laterally outside the car wheels and between the longitudinal upright planes of the outermost portions of the side closure walls and extending above and below the horizontal plane of the centers of the car axle journals, a central lading bottom and side lading wing body portions having lading bottoms each located in a horizontal plane cutting the car wheels on the same side of the car and apertured to receive the car wheels and including hood-coverings over the car wheels.
51. In a mine or similar rail car, the combination of car axle journals, a lading body including a lading bottom having at least substantial portions below the horizontal plane of the tops of the car axle journals, car wheels projecting into the lading body of the car, straight longitudinal load-supporting side sills located outside the car wheels and between the longitudinal upright planes of the outermost portions of the side closure walls and extending above and below the horizontal plane of the centers of the car axle journals and extending from axle to axle, and hood-coverings over the car wheels.
52. In a mine or similar rail car, the combination of a lading body structure including a central sub-axle bottom portion, car wheels, car axle journals, an end closure wall, a central lading body extending longitudinally, side lading wing-bodies at least one of which has a bottom portion between the said end closure wall and the adjacent wheel lying below the horizontal plane of the top of the said wheel, longitudinal sill-means as parts of the lading body structure oppositely disposed and of sufficient stiffness as separate elements to support the lading load without harmful end-drooping and having portions extending above and below the horizontal plane of the axes of the car wheels, and an axle support means lying laterally outside a car wheel and attached to the lading body structure.
53. In a mine or similar rail car, the combination of oppositely disposed side-beams as separate lading body supporting elements, side closure wall portions laterally outside adjacent side-beams; an end structure rigidly attached to the side beams and including an upright end channel extending transversely between and perpendicular to the side-beams, a metal bumper member having an upright metal bumping face-means and a horizontal metal flange directed therefrom towards the lading body of the car, and a filler

member extending outwardly from the web of said upright end channel to the said face-means; and a sub-axle lading bottom in rigidly secured relationship to both said side-beams and said end channel and bracing the same against twisting and warping.

54. In a mine or similar rail car, the combination of car wheels, a lading body structure including wheel recessed wing lading bodies and side closure walls with upright outer portions, stiff longitudinal side beams as separate elements for supporting the lading body without harmful end-drooping and located between oppositely disposed upright outer portions of the side closure walls and also between oppositely disposed car wheels and extending longitudinally substantially from end to end of the lading body; said lading body structure also including a stationary sub-axle central lading bottom rigidly secured to the side beams and bracing them against warping and twisting, and also including wheel hood-coverings extending over the tops of the wheels, said wing lading bodies providing an uninterrupted space outwardly of each wheel so that access to and the axial removal of the corresponding wheel from its axle may be effected, and sealing means connecting the hood coverings and the side closure walls.

55. In a mine or similar rail car, the combination of a traction truck consisting of axles and wheels on the axles and longitudinal side members, axle boxings on said side members, axle tubes resting loosely and turnably in said boxings, and bushings seated in said tubes and surrounding the axles.

56. In a mine or similar rail car, the combination of a traction truck consisting of axles and wheels on the axles and longitudinal side members, axle boxings on said side members, and axle tubes surrounding the axles and resting loosely and turnably in said boxings and having an external member bearing loosely against the inner ends of said boxings.

57. In a mine or similar rail car which is to be bodily shifted to dumping position for emptying, the combination of wheels and axles, side lading-containing walls extending above and below the plane of the axles, an end structure including bumper and coupling means, a central sub-axle lading bottom, lading wing bottoms intersecting the longitudinal planes of the wheels below the tops of the wheels and apertured to receive the wheels, and wheel hood-coverings having upright longitudinal closure walls both outside and inside the adjacent wheels, said walls providing a substantially unobstructed lading space from which the lading may be discharged by bodily shifting the car.

58. In mine and similar rail cars, the combination of side sills with lower sections having upright walls, car axles supporting the side sills and having journals, wheels supporting the car axles, an end traction transverse structure including a transverse metal member with a stiffening flange, a bumper member, a central lading bottom located at least in substantial part below the plane of the tops of the car axle journals, and also below the horizontal plane of the upper portions of the upright walls of the side sills, a side lading wing bottom extending through the vertical longitudinal plane of the inside of the car wheel flanges on the same side of the car and having portions located in a plane inclined to the horizontal at a lesser angle than the angle of repose of loose coal and similar lading, and a part

of each of said wheels on said side projecting through the plane of the said lading wing bottom between the ends of said wing bottom.

59. In a mine or similar rail car, the combination of longitudinal load-supporting side members with substantially upright lower sections, car wheels, car axles having journal centers located in a horizontal plane cutting the said upright sections, wheels for supporting the axles, end sill traction structures including bumper means and coupling means, a central lading bottom extending longitudinally between end structures and rigidly attached to at least one said end traction structure and of substantially rectangular perimeter and with a portion thereof located in a horizontal plane below the horizontal plane of the tops of the axle journals and cutting the upright sections of the side members, a side lading wing bottom portion extending laterally outward substantially from the vertical face of the said upright sections of one of the said side members and extending through the upright plane of the inside of the flanges of the car wheels at the same side of the car and located in a plane cutting the said wheels, and a deep hood-covering over at least one car wheel on such side of the car.

60. In a mine or similar rail car, the combination of car axles, car wheels, side sills intersecting the horizontal plane of the centers of the journals of the car axles, a plate metal lading bottom having its lowest portions located in a horizontal plane substantially at the level of the horizontal plane of the lowest portions of the side sills, and other portions of the lading bottom extending laterally beyond said side sills to form lading wings, and metal wheel hood-coverings each having longitudinal closure walls at both inner and outer faces.

61. In a traction truck frame for a mine or similar rail car having side sills, an end traction structure including a transverse metal member having an upright web which is adapted to be secured to the side sills and having also a lower horizontal outwardly directed flange, and said end structure also including a metal member having an upright section overlapping the said upright web and secured thereto and having a horizontal section extending outwardly at least as far as the said lower flange, and a draw-bar extending longitudinally past the upright section and having a portion extending downwardly below the top of the upright section and secured in rigid relation thereto, and also having a substantially horizontal portion providing a part of the structure for transmitting draft stresses to another car.

62. In a mine or similar rail car having car wheels and axles with axle journals; side sills; a lading body with an end wall and a plate metal lading bottom secured to the side sills and located at least for a major portion below the horizontal plane of the axle journals; said side sills extending from end to end of said lading body; and an end traction structure comprising in part an extension of the lading bottom beyond the junction of said end wall and said bottom and in part a transverse metal structure located at least in part above said major portion of the bottom and secured to said extension and having a portion apertured to receive a coupling pin, and a draw-bar member secured to said bottom and including an apertured portion spaced from said first apertured portion to receive the coupling pin.

63. In a mine or similar rail car having car

- wheels and axles with axle journals; side sills, a lading body with an end wall and a plate metal lading bottom secured to the side sills and located at least for a major portion below the horizontal plane of the axle journals; said side sills extending from end to end of said lading body; and an end traction structure comprising in part an extension of the lading bottom beyond the junction of said end wall and said bottom, and 5 a draw bar member secured to said bottom and having a part spaced from said extension and apertured to receive a coupling pin, said end structure also including a portion located above said major portion of the bottom and also having an aperture for the coupling pin.
64. In mine and similar rail cars, a traction truck frame comprising side members and end members, at least one said end member having an upright wall, a lading bottom secured to the 10 side members substantially at their lower edges and including a portion extending upward at an end of the car and beyond the corresponding end member and draft-transmitting means apertured for receiving a coupling pin, said end member including a draw-bar member spaced from said draft-transmitting means whereby to receive a coupling link and being apertured in alignment with the aperture in said draft-transmitting means to receive a coupling pin.
65. In mine and similar rail cars, the combination of side sills, car wheels and axles, an end traction structure, and bottom, side and end wall means for completing the lading body; the bottom including sub-axle plate metal portions attached to the side sills and having a longitudinal extension at an end, said end traction structure including a plate metal member secured to said lading bottom at points spaced from the transverse edge thereof, said plate metal member including one portion extending upwardly from the bottom and at an acute angle relative thereto and also including another portion substantially parallel to but spaced from said extension, and a transverse metal end sill member connected to the side sills, to said extension and to said 20 plate metal member.
66. In a mine or similar rail car, the combination of car wheels, car axles having journals, side beams, axle boxings guided from said side beams and movable with respect thereto, the 25 horizontal plane of the axle journals intersecting the side beams, a lading body located at least in part below the horizontal plane of the tops of the axle journals, shock absorbing means interposed between the axle boxings and said side beams and bottom, a cross tie member connected to said boxings and extending from one boxing to another in spaced relationship to the axle, and shock absorbing means interposed between the 30 cross tie and said beams and bottom.
67. In a mine or similar rail car, the combination of car wheels, car axles having journals, side sills extending from end to end of the lading-receiving portion of the car and located inside the car wheels, a lading body structure including a lading bottom located at least in part below the horizontal plane of the tops of the axle journals and secured to the side sills, axle guiding structures for controlling the axles during 35 upward and downward movements of the individual wheels with respect to the body and pivoted to said side sills, and means for limiting the pivotal movement of said axle guiding structures.
68. In a mine or similar rail car, the combination of side beams, car axles having journals, 40
- said journals being located wholly above the lower portions of the side beams, a composite end structure including a channel member, and a stationary sub-axle lading bottom including a substantially horizontal portion extending between and rigidly attached to the said lower portions of the side beams and rigidly attached to the said channel member for bracing said side beams and end structure with relation to one another.
69. In a mine or similar rail car, the combination of side beams, car axles having journals, said journals being located wholly above the lower portions of the side beams, an end beam of approximately channel shape connected to said side beams above the lower portions thereof, and a stationary sub-axle lading bottom including a substantially horizontal portion extending between and attached to said side beams at the said lower portions thereof and attached rigidly 20 to the end beam for bracing said side and end beams with relation to one another.
70. In a mine or similar rail car, the combination of a supporting and substantially rectangular traction truck frame with stiff load-supporting side sill-members and with transverse end members rigid in respect of the side members, car axles whose journals lie in a horizontal plane cutting the side sill-members, wheels supporting the axles and located outside the side sill-members, a lading body including a lading bottom between the side sill-members, side lading bottoms extending laterally outward from the side sill-members and located in planes cutting the adjacent car wheels and at least in part below 30 the horizontal plane of the tops of the axle journals, substantially upright longitudinal closure sides laterally outside the adjacent car wheels, and bracing and supporting means located close to said wheels for connecting the side sill-members of the traction truck frame with the said adjacent closure sides.
71. In a mine or similar rail car, the combination of longitudinal flanged metal side sill-members sufficiently stiff as separate load-supporting elements to support the lading load without harmful end-drooping and extending substantially from end to end of the lading body of the car and having upright wall-portions, a sub-axle lading bottom section, car wheels located outside 40 sill, car axles each having a portion intersecting the upright plane of the outer face of the wall-portion of the adjacent side sill-member between the respective horizontal planes of the top and bottom edges of said side sill-member, and at 45 least a part of the said wall-portion below the said axle portion being cut away whereby vertical movement of said axle portion in respect of said side sill-member is permitted for lessening the chance of derailment of the car on an uneven track.
72. In a mine or similar rail car, the combination of a lading body structure with side closure walls having outer upright portions, car wheels, car axles, flanged metal side sill-members as 50 separate elements located between oppositely disposed wheels and inwardly spaced from the planes of the outer upright portions of the side closure walls and extending longitudinally substantially from end to end of the lading body and being sufficiently stiff to support the lading body against harmful end-drooping, and lading wing-bodies each including a lading wing-bottom laterally outside of adjacent sill-members and having at least a portion located below the hori- 55
- 75

- zontal plane of the axes of the car wheels and having another portion extending transversely and serving as bracing and supporting means for the lading-wing bodies.
- 5 73. In a mine or similar rail car, the combination of car wheels, stiff metal longitudinal side-sill members, a metal sub-axle lading bottom rigidly attached to the longitudinal sill-members and extending transversely from one sill-member 10 to the other, end closure walls, and side closure walls with upright portions spaced laterally from the adjacent sills, the sill members being sufficiently strong to support the lading load without the reinforcement of the elements composing the 15 side and end closure walls, wheel coverings each having a substantially upright longitudinal wall inside the corresponding wheel and forming a part of the adjacent side closure wall of the lading body and extending below the horizontal 20 plane of the axes of the car wheels.
74. In a self-clearing end-dump mine car for discharging all its lading at its forward end under a movable gate, the combination of a lading body, car axle journals, a traction truck frame comprising stiff longitudinal side sills and stiff transverse end sills rigidly associated whereby the said frame independently of the walls and bottom of the lading body is sufficiently stiff to take the 25 bumping strains of the car and supporting the lading load against end drooping, lading body side closure walls, car wheels laterally outside of the adjacent side sills and having flanges lying in upright planes inside of the upright planes of the upper portions of the said adjacent side closure walls, a lading bottom structure having at 30 least portions extending transversely from side sill to side sill and extending centrally and longitudinally beyond the wheels towards the ends of the lading body, and the said lading bottom structure having at least portions of its top surface lying below the horizontal plane of the tops of the axle journals and also below and to the rearward of the upper portions of the forward transverse end sill, and gradually sloping deflector means as part of the car structure whereby all the lading upon the central portion rearward of and below the higher forward portions of the end sill will be deflected and pass over the end sill and be effectively discharged when the 35 car is tilted forward for end dumping.
75. In a self-clearing end-dump mine car for discharging all its lading at its forward end under a movable gate, the combination of car wheels, car axles between oppositely disposed wheels, a longitudinally central sub-axle lading bottom structure having portions of its top surface both rearward and forward of an axle located below the level of the top of the said axle, the lading body structure providing a lading-deflector surface leading from at least some of the said low rearward portions to the top of the said axle whereby at least some of the lading moves readily from a lower level to the higher level of the said axle whereby the lading may pass forward in the 40 lading body and be effectively discharged when the car is tilted forward for end-dumping, and the average slope of the said deflector-means to the rear of the top of the said axle being less steep than the average slope through which the lading travels downward immediately forward of the said axle.
76. In a self-clearing end-dump mine car for discharging all its lading at its forward end under a movable gate, the combination of a lading body 45 with side closure walls with laterally outside up- right portions, a lading bottom, car wheels, oppositely disposed longitudinal side sills as separate elements located between oppositely disposed upright portions of side closure walls and extending substantially from end to end of the 5 lading body for supporting the lading load against end drooping, means for sealing the side-sills to the adjacent lading body structure, a bumping structure at the forward discharge end of the car, and a lading bottom structure having at least portions extending transversely between the upright longitudinal planes of the lower portions of the side sills and extending centrally and longitudinally towards each end of the car beyond the car wheels, and the said bottom structure having at least portions of its top surface lying below the horizontal plane of the axes of the car wheels and having portions which are at a lower level than portions of the said forward bumping structure, said car structure also providing a deflector surface for causing all lading which is below and also directly rearward of the said portions of the forward bumping structure to be gradually deflected in respect of the said forward portions whereby it will be effectively 10 discharged when the car is tilted forward for end-dumping.
77. In a self-clearing end-dump mine car for discharging all its lading at its forward end through a single and relatively unobstructed opening created at its forward end by the relative movement of at least one gate when the car is tilted forward for end-dumping, the combination of car wheels, side sills supported from the wheels, an end structure extending from side sill 15 to side sill and including a bumper at the discharge end of the car; a lading body sealed to the said end structure whereby no lading can be discharged underneath the said end structure, including a lading bottom structure having at 20 least portions below the horizontal plane of the axes of the car wheels and having portions also below the top parts of the end structure that lie directly forward longitudinally, the car structure also providing deflector surfaces at said forward 25 end for causing all the lading which is both below and longitudinally rearward of said higher parts of the forward end structure to be deflected and discharged through the said opening when the car is tilted forward for end-dumping.
78. In a self-clearing end-dump mine car for discharging all its lading at its forward end through a single and relatively unobstructed opening created at its forward end by the relative movement of a lifting end gate when the car is tilted forward for end-dumping, the combination of car wheels, side sills, an end structure extending from side sill to side sill and including a bumper at the discharge end of the car; a lading body sealed to the said end structure whereby no lading can be discharged underneath the said end structure, including a lading bottom structure having at least portions below the horizontal plane of the axes of the car wheels and having portions also below the top parts of the end structure that lie directly forward longitudinally, the car structure also providing deflector surfaces at said forward end for causing all the lading which is both below and longitudinally rearward of said higher parts of the forward end structure to be deflected and discharged through the said opening when the car is tilted forward for end-dumping, and a lifting end gate having hinge arms fixed to the closure portion and extending substantially parallel to the side walls 30

of the lading body and pivotally mounted thereon at a point spaced rearwardly from the front end of the car.

79. In a self-clearing end-dump mine car for discharging all the lading of its lading body through an open space created by the relative movement of a single gate at its forward end when the car is tilted forward for end-dumping, the combination of car wheels, a rear end closure wall to the lading body, a longitudinally extending central lading bottom lying between oppositely disposed car wheels and having at least portions of its top surface located below the horizontal plane of the axes of the car wheels, longitudinally extending side lading wing-bodies having lading bottoms with portions of their top surfaces between the upright transverse plane of the rear car wheels and the rear closure wall lying substantially below the top parts of the adjacent wheel to afford increased capacity longitudinally rearward of the rear wheels, the lading body structure also providing deflector surfaces whereby lading on the said portions of the wing lading bottoms substantially below the said top parts will be gradually deflected past the said top parts whereby it will be discharged from the front end of the car when the car is tilted forward for end-dumping.

80. In a self-clearing end-dump mine car for discharging all its lading through a single open space created by the relative movement of at least one forward end gate when the car is tilted forward for end-dumping, the combination of two pairs of oppositely disposed car wheels, a rear end closure wall to the lading body, a lading bottom structure having at least parts of its top lading bottom structure located below the horizontal plane of the axes of the car wheels, and parts of the lading bottom surface in the upper longitudinal plane cutting two car wheels on one side of the car between the rearward of the two wheels and the rear end closure wall and also between the forward of the two wheels and the forward part of the lading body being located substantially below the top portions of the said two wheels to give a large capacity below the tops of the wheels, the structure of the lading body providing wheel coverings including deflector surfaces whereby the lading on the said parts of the lading surface between the rearward of the two wheels and the rear end closure wall will be deflected gradually whereby it will readily pass upward and over the said two wheels directly forward and whereby it will be effectively discharged from the front end of the car when the car is tilted forward for end-dumping.

81. In a self-clearing end-dump mine car for discharging all its lading at its forward end through a single open space when the car is tilted forward for end-dumping, the combination of car wheels, a lading bottom structure having at least portions of its top surface located below the horizontal plane of the axes of the car wheels, a rear end closure wall for the lading body, a transversely extending bumper structure at the discharge end of the car, other walls cooperating with the bottom structure and end closure wall to provide a lading body sealed to the said bumper structure so that no lading can be discharged underneath said bumper structure, portions of the surface of the lading bottom structure being located below the top parts of the bumper structure that lie directly longitudinally forward thereof, the lading body structure providing first deflector surfaces by which all the lading which is below the

level of the top of longitudinally aligned parts of the forward bumper structure will be deflected gradually and be readily discharged past the bumper structure when the car is tilted forward for end-dumping, other portions of the top surface of the lading bottom located between the rear end closure wall and the transverse upright plane of the rearward oppositely disposed wheels being located substantially below the top parts of the said rearward wheels, the lading body structure also providing second deflector surfaces by which the lading on the said other portions of the lading bottom surface which is in longitudinal alignment with and substantially below the level of the top parts of the said rearward wheels may be gradually deflected over the said rearward wheels so that this lading can readily move forward for discharge at the front end when the car is tilted forward for end-dumping.

82. A car as in claim 81 in which there are transverse car axles between oppositely disposed wheels, and in which rear portions of the top surface of the lading bottom longitudinally rearward of the rearmost axle lie substantially below the level of the top of the said rearmost axle, said lading body structure also including deflector surface means at said rearmost axle by which lading lying on said rear portions will be deflected gradually for passing over the top of the said rearmost axle so that the lading can readily move forward for discharge at the front end when the car is tilted forward for end-dumping.

83. In a self-clearing end dump mine car for discharging all its lading at its forward end through a single open space when the car is tilted forward for end-dumping, the combination of car wheels, car axles connecting oppositely disposed car wheels, a lading bottom structure forming part of a lading body structure and having rear portions of its top surface rearward of the rearmost axle located substantially below the level of longitudinally aligned top parts of the said rearmost axle, axle deflector-means by which the lading lying on the said rear portions of the top surface of the lading bottom below the said top parts of the said axle will be deflected gradually for passing over the top of the said axle when the car is tilted forward for end-dumping, a transversely extending bumper structure at the discharge end of the car, other walls included in the lading body and sealed to the said bumper structure so that no lading can be discharged underneath the said bumper structure, front portions of the top surface of the lading bottom structure lying below the level of the top of longitudinally aligned parts of the said bumper structure, the lading body structure providing deflector surfaces by which all the lading lying on said front portions will be deflected gradually for passing the said bumper structure and be effectively discharged when the car is tilted forward for end-dumping.

84. In an end-dump mine or similar rail car, the combination of side closure walls having portions lying in upright planes, load-supporting longitudinal side members laterally spaced from the planes of said upright portions, wheels, axles, bumper and coupling means at the ends of the car, a plate metal central bottom located in substantial part below the horizontal plane of the tops of said axles and sloping upwardly at one end toward the adjacent bumper and coupling means whereby to deflect the lading over said means during end dumping, wing bottoms extending laterally from said central bottom and inter-

- secting the upright longitudinal planes of the wheel flanges below the tops of the wheels, and wheel coverings rigid with the wing bottoms and extending over the wheels.
85. In end-dumping mine and similar rail cars, the combination of longitudinal metal load-supporting side sill-members with substantially upright sections, the said members serving at least in part as lading body closure walls, car axles having journals located in a horizontal plane cutting the said upright sections, an end traction structure rigid in respect of the said side sill-members and including a metal bumper member, a securely fastened lading bottom at least in substantial part located between the upright planes of the upright sections of the side sill-members and having at least portions located below the horizontal plane of the tops of the axle journals and also below the horizontal plane of the upper portions of the end traction structures, lading wing bottom portions located in planes cutting the adjacent wheels, and wheel deflector means whereby the lading is carried over the tops of the wheels when the car is tilted for end-dumping.
86. In end-dumping mine and similar rail cars, the combination of longitudinal metal load-supporting side sill-members with substantially upright sections having sidewise extending stiffening sections, the said sill-members serving at least in part as lading body closure walls, car axle journals whose centers lie in a horizontal plane cutting the upright sections of the longitudinal side sill-members, wheels on the axle journals, a rigidly related traction end structure including a bumper member, a stationary secured central lading bottom located at least in substantial part between the upright longitudinal planes of the side members and having at least substantial portions below the plane of the tops of the axle journals, and an end structure deflector means sloped to carry the lading from the said portions of the central lading bottom over the top of the end traction structure when the car is tilted for end dumping and a lading wing bottom wall having a plane portion extending laterally outward through the vertical longitudinal plane of the inside of the flanges of the car wheels on the same side of the car with the plane of the said bottom wall cutting the wheels on said side.
87. In end-dumping mine and similar rail cars, the combination of car axles having journals, longitudinal side load-supporting metal members with substantially upright lower sections and sidewise extending stiffening sections, the said longitudinal members at least in part serving as lading body closure walls, said axle journals having their centers located in a horizontal plane cutting the said lower sections of the longitudinal metal members, wheels for supporting the axles, a securely fastened central lading bottom located intermediate the upright longitudinal planes of the longitudinal metal members and having at least substantial portions located below the horizontal plane of the tops of the axle journals and also below the horizontal plane of the upper portions of the longitudinal members, an axle deflector means rising from the said central lading bottom at a low angle approximately to the horizontal plane of the top of a car axle whereby the lading is deflected over the axle when the car is tilted for end-dumping, a lading body wing extending through the vertical longitudinal plane of the inside of the flanges of the car wheels on the same side of the car with the plane of the said bottom wall cutting the wheels on said side.
88. In an end-dump mine or similar rail car, the combination of wheels, car axles having journals, a lading body including a stationary lading bottom with a central portion and with wing portions laterally outside the adjacent wheel flanges, parts of the lading bottom being located below the plane of the tops of the axle journals, longitudinal lading-body load-supporting metal means located laterally outside the said central portion of the lading bottom, said wheels projecting into apertures of the wing portions of the lading bottom, and coverings closing the apertures and extending over the tops of the said wheels and so sloped that all the lading between wheels and rear end of the car can pass over them and clear such portions of the car when the car is tilted for end dumping.
89. In an end-dump mine or similar rail car which is to be tilted forward for end-dumping, the combination of wheels axles having journals, metal sill-members having bottom flanges thereon below the horizontal plane of the tops of the axle journals, and a plate metal floor securely fastened to the flanges of the sill-members and including axle deflectors between the sill-members, said deflectors each having a gradual slope rearward of the transverse upright plane of the corresponding axle for deflecting the lading over the axle during dumping and having a more abrupt slope forward of said upright plane for providing a larger lading capacity in said car.
90. In a mine or similar rail car, the combination of stiff flanged metal side beams as separate elements for supporting the lading load without harmful end-drooping, a transversely extending and end bumping and haulage structure including a wood cushion and an upright metal bumping-face member with a metal flange extending horizontally on the surface of the wood cushion towards the lading body of the car and having an upright coupling pin aperture approximately at the transverse center of the said bumping and haulage structure, the said aperture extending through the said horizontal flange and wood cushion, a draw-bar extending above said aperture and being apertured in alignment therewith, car wheels, and a lading bottom structure having at least portions located below the horizontal plane of the axes of the car wheels and the said bottom structure including sections extending across the space between the side beams and rigidly fastened to the side beams so that the said beams are braced against warping and twisting under the haulage strains and stresses.
91. In a mine or similar rail car for operating in trains, the combination of car wheels, means providing a traction truck frame for taking the haulage strains and stresses and for supporting the lading load without harmful end-drooping; the said frame means comprising as elements thereof two flanged metal side-sills oppositely disposed between the upright planes of the oppositely disposed sides of the car and extending longitudinally of the car substantially from end to end and having substantially upright lower portions that are located at least in part below the horizontal plane of the axes of the car wheels, and the said frame means comprising also a longitudinal central lading bottom structure passing transversely from side-sill to side-sill and rigidly attached to both side-sills and bracing same against warping and

twisting, at least portions of the said lading bottom structure being located below the said horizontal plane, and also comprising end sill structures perpendicular to and rigidly attached to the 5 side-sills so as to constitute a metal frame of rectangular inside perimeter, one said end sill structure including a metal member having at least one flange directed away from the lading body and including a deep transverse bump-cushioning means located at least in part in overlapping relation with the said flange, and including also a transverse metal bumper member with an upright bumping face and at least one horizontal flange directed towards the lading body of the 10 car; end and side closure walls, and sealing means 15 as separate elements from the said frame means for sealing the said frame to the said closure walls.

92. In a mine or similar rail car, the combination of car wheels, a lading bottom structure at 20 least a substantial part of which lies below the horizontal plane of the axes of the car wheels, side and end closure walls, and means providing a traction truck frame as a separate element from 25 the upper side and end closure walls and the sealing means therefor, the said frame means including stiff metal side beams extending substantially from end to end of said bottom structure and disposed between oppositely disposed wheels 30 and being rigidly associated with a central section of the lading bottom structure extending between the oppositely disposed side beams so that the said side beams are reinforced against warping and twisting, and the said frame means including 35 an end structure extending transversely between and rigidly attached to the ends of the side beams and including a stiff transverse metal angle with an upright wall perpendicular to the side beams and a metal plate in a horizontal 40 plane secured to and reinforcing the said angle and a transverse cushioning means secured to the said angle, at least a major portion of said upright wall being located above the level of said low part of the lading bottom structure, and a coupling pin 45 in a transverse upright plane cutting the said cushioning means.

93. In a mine or similar rail car for operating in trains, the combination of car wheels, end closure walls, a lading bottom, a traction truck 50 frame including side sills each extending substantially from one end closure wall to the other, said sills having upright lower portions disposed between oppositely disposed car wheels and including an end traction structure perpendicular 55 to and rigidly attached to the side sills and including as transversely extending members at least one metal angle-form member with an upright wall perpendicular to and attached to the side sills, and one heavy transverse wood-filler 60 member located outside of and bearing against the said upright wall, the said end traction structure also including a metal bumper having an upright bump-resisting metal face and a horizontally extending flange integral with the said 65 face and overlapping said wood-filler member, a coupling pin lying in an upright transverse plane intersecting the said wood-filler longitudinally beyond the said upright wall, at least a major portion of said upright wall being located above the 70 level of the lowest portion of the lading bottom, and sealing means as independent elements for connecting the said metal angle-form member with portions of the end closure wall and the lading bottom.

75 94. In four-wheel mine or similar rail cars

with sub-axle lading bottoms and for operating in trains, the combination of car axles, means providing a lading-load supporting frame located at the lowest part of the lading body structure of the car, the said frame means being the means 5 for transferring the haulage strains and stresses from one car to another in the train and the said frame means comprising two metal side-sill means with longitudinally extending upright side-wall portions having sidewise extending 10 stiffening portions, each said side means passing in a straight line substantially from end to end of the lading body and serving at least in major part as a means for supporting without harmful end-drooping the portion of the lading 15 load which is located longitudinally beyond the car axles, and the said frame means also comprising two stiff bump-absorbing flanged metal end-means extending transversely between the 20 said upright side-wall portions of the sill means and in rigid association therewith, and the said end-means having upright wall portions, the four said upright wall portions being in the same horizontal plane and serving at least in part as lading retaining walls, a metal sub-axle lading bottom 25 rigidly attached to the said side-sill means and the said bottom forming a part of the said frame means and bracing the said side-sill means against warping or twisting, bump cushioning means as a part of the frame means located at 30 least at one end of the car and located beyond and in free abutment relationship with the upright wall portion of the adjacent metal end-means, an upright metal bumping-face-means 35 as a part of the said frame means, and the said cushioning means extending outwardly towards the said bumping-face-means and in free abutment relationship therewith and extending transversely in respect of the said side-sill means whereby the bumping stresses are cushioned before they reach the said side-sill means and 40 whereby the said stresses are transferred sidewise whereby they come more directly in line with and are more efficiently absorbed by the side means.

95. In a mine or similar rail car, the combination of car axle journals, longitudinal load-supporting side sills with substantially straight and upright lower sections intersecting the horizontal plane of the centers of the axle journals, 50 axle support means connected to the car structure between oppositely disposed wheels, car wheels outside the said upright lower sections, a stationary sub-axle lading bottom extending from side sill to side sill, wing lading bottoms 55 extending outwardly from approximately the bottom levels of the side sills in approximately horizontal planes.

96. In a mine or similar rail car, the combination of a substantially rectangular traction truck 60 frame including side sills, car axles including journals, car wheels located outside the frame, axle boxings located between the wheels, a lading body supported by said frame and including portions extending laterally past the wheels, said 65 sills extending upward into the lading body, and a wheel hood-covering extending over a said wheel and extending downward below the horizontal plane of the tops of the axle journals.

97. In an end-dump mine or similar rail car, 70 the combination of car axles including journals, car wheels, a bumper at the forward end of the car, a secured stationary lading bottom floor-structure including one part below the level of said bumper and another part rising obliquely 75

for discharge of the lading over the bumper when the car is tilted forward for dumping, said floor-structure also including parts located rearwardly of and longitudinally aligned with the rear wheels and located at a level below the tops of said wheels and also including parts extending in hood-form over said wheels and slanting rearward from the rear wheels to serve as deflectors for the longitudinal discharge of the lading past the wheels when the car is tilted forward for dumping.

98. In a mine or similar rail car, the combination of wheels, side sill-members having substantially upright lower wall portions, a transverse end structure connected to said sill-members, axles having journal centers located in a horizontal plane cutting the said upright walls, a secured metal plate supported by said side sill-members and having a central portion forming a substantially continuous and rectangular sub-axle central lading bottom, said metal plate also extending laterally and substantially continuously beyond said side sill-members to form lading wings, and bump-resisting cushion members supported by said end structure.

99. In a mine or similar rail car which is to be bodily shifted to dumping position for emptying, the combination of car wheels and axles having journals, upright longitudinal side closure walls located laterally outside the wheels and having their lower edges located below the horizontal plane of the tops of said journals, a rigid end structure including bumper and coupling means, a lading bottom having a portion extending substantially continuously in a single plane from one of said upright side walls to the other and having the lading surface area of a major part of said portion located below said horizontal plane, and side sills extending substantially from end to end of the lading bottom and located in inwardly spaced relationship to said closure walls, said sills extending upwardly into the lading space so that lading may rest upon said bottom at points both between and outside of said side sills and below the tops of said side sills, and lading may be discharged therefrom by bodily shifting the car to emptying position.

100. In a mine or similar rail car which is to be bodily shifted to dumping position for emptying, the combination of car wheels and axles having journals, side sills extending substantially from end to end of the lading-receiving portion of the car, upright longitudinal side closure walls located laterally outside the wheels and outside the side sills and having their lower edges located below the horizontal plane of the tops of said journals, a rigid end structure including bumper and coupling means, a substantially continuous lading bottom of substantially rectangular perimeter extending from one of said upright side walls to the other and having the lading surface of a major portion thereof located below said plane, said sills extending upwardly into the lading space so that lading may rest upon said bottom at points both between and outside of said side sills and below the tops of said side sills, and lading may be discharged therefrom by bodily shifting the car to emptying position.

101. In a mine or similar rail car which is to be bodily shifted to dumping position for emptying, the combination of car wheels and axles having journals, side sills extending substantially from end to end of the lading-receiving portion of the car, upright longitudinal side closure walls located laterally outside the wheels and outside

the side sills and having their lower edges located below the horizontal plane of the tops of said journals, a substantially continuous lading bottom extending from one of said upright side walls to the other and joined to the said walls adjacent their lower edges, said bottom having deep hood-form extensions extending over said wheels and connected to and supporting said lading bottom adjacent said side walls, said sills extending upwardly into the lading space so that lading may rest upon said bottom at points both between and outside of said side sills and below the tops of said side sills, and lading may be discharged therefrom by bodily shifting the car to emptying position.

102. In a mine or similar rail car, the combination of car wheels and axles, a lading body including a secured stationary sub-axle central lading bottom in bracing relationship, longitudinal load-supporting side members, an end traction structure in rigid relationship with the side members and including a flanged metal cross member connected to sills having an upright wall and including also two metal bumper members providing laterally spaced upright bumping faces separated by a recess and a coupler attachment member in said recess, the said metal bumper members having flanges directed towards the lading body and having wood filler members.

103. In a mine or similar rail car, the combination of car wheels, car axles having journals, a lading body structure including a lading bottom located at least in part below the horizontal plane of the tops of the journals of the car axles and also including means for stiffening the body against end drooping, the said stiffening means being located between oppositely disposed wheels, axle boxings located inside the corresponding wheels and guided directly by said stiffening means, and a shock absorbing means between the axles and the lading body structure.

104. A low bottom car including upright wall portions, center and end bottom metal plates having substantially straight adjacent transverse edges which extend substantially parallel to one another from side sill to side sill and are spaced apart below the car axles, spaced metal longitudinal side sills extending from end to end of the car between the wheels and rigidly attached to said bottom plates and braced thereby, axles located in the gaps between the bottom plates with their axes above said edges, and pieces including arched portions extending over the axles and connected at the bottom plates and extending between the side sills for closing the bottom between the plates and the side sills.

105. A low-bottom car including center and end bottom metal plates having substantially straight adjacent transverse edges which extend substantially parallel to one another from side sill to side sill, said plates projecting laterally beyond the side sills, said edges being spaced apart to constitute gaps, spaced metal longitudinal side sills extending from end to end of the car between the wheels, axles located at the gaps between the bottom plates and with their axes above said edges, side lading walls sealed to the longitudinal edges of said metal plates, and fixed pieces including arched portions extending over the axles and from side sill to side sill for closing the bottom between the plates and the side sills and between the side sills and the side lading walls.

106. A low bottom car including a metal bottom and side walls in rigid relationship thereto; longi-

- tudinal sills in secured relationship to said bottom and located above low portions thereof; said sills being spaced apart throughout their lengths; axles for supporting the sills and having journals located above said bottom; and end structure connected to the ends of the sills and to the bottom and including an end lading-retaining wall portion, and pumper and coupling means fixed to said end wall portion and located above the bottom; wheels on said axles, portions of said bottom being constructed and arranged to provide wheel covers extending over said wheels between the side walls and the sills and in secured relationship to said side walls, other portions of said bottom and said sills whereby to provide a transverse support for lateral portions of the bottom between the ends of the car and to close the holes between the side walls and the sills, and pieces including arched portions extending between said longitudinal sills for receiving the axles and connected to said bottom whereby to close said holes between the sills and operate with said transverse support for stiffening the car.
107. A low bottom car including a metal bottom and side walls in rigid relationship thereto; longitudinal sills in supporting relationship to said bottom and located above low portions thereof; said sills being spaced apart throughout their lengths; axles for supporting the sills and having journals located above said bottom; an end structure connected to the ends of the sills and to the bottom and including an end lading-retaining wall portion, and bumper and coupling means fixed to said end wall portion and located above the bottom; wheels on said axles, portions of said bottom being constructed and arranged to provide wheel covers extending over said wheels between the side walls and the sills and in secured relationship to said side walls, other portions of said bottom and said sills whereby to provide a transverse support for lateral portions of the bottom between the ends of the car and to close the holes between the side walls and the sills, and pieces including arched portions extending between said longitudinal sills for receiving the axles and connected to said sills whereby to close said holes between the sills and operate with said transverse support for stiffening the car.
108. In the end sill structure for a mine or similar rail car having side sills, the combination of a stiff metal member for forming an end sill of the car and passing perpendicularly from side sill to side sill and rigidly secured to the ends thereof and having a horizontal flange directed away from the center of length of the car, a bumper element beyond the said metal means and overlapping the said flange and guided thereby so as to be movable longitudinally of the car in respect of the metal member, the said bumper element having an upright metal bumping face, and spring means for transmitting bumping stresses from the said metal bumping face to the said metal member in cushioned fashion at points spaced at each side of the central longitudinal upright plane of the metal member when positioned in a car for delivering bumping stresses to the metal member in cushioned fashion and for cushioning abrupt centrally directed bumping shocks and transferring said shocks upon the bumper element at least in part laterally toward the said side sills whereby the bending strain upon the end sill is lessened.
109. In a mine or similar rail car, the combination of wheels, axles; a lading body including

side closure walls outside of oppositely disposed wheels, end closure walls, and a lading bottom; two flanged metal beams each extending longitudinally of the lading body and towards the end closure walls, the said beams being located between oppositely disposed wheels and constituting the means for substantially preventing the end-drooping of the lading body, the said beams projecting above the lading bottom at least in part and into the lading body so that lading space is provided on both sides of portions of each of the said beams in the horizontal planes of the said portions.

110. In a mine car, the combination of a lading body having side and end closure walls and a lading bottom, side sill members which, of themselves and independently of the elements composing the lading bottom, the side closure walls, and the end closure walls of the lading body, serve as essential load supporting beams for preventing the lading body from end drooping, the said sill members extending substantially from end closure wall to end closure wall and projecting at least in part into the lading body space so that lading space is provided on each side of portions of each of the said sill members in the horizontal planes of the said portions.

111. In a mine or similar rail car, the combination of side beams, car axles above the lower portions of the side beams, a transverse end structure connected to the side beams, a stationary sub-axe lading bottom secured to the end structure at a low level thereof, and a longitudinally extending end thrust means rigidly attached to the bottom and in abutting relation with the end structure at a high level of the latter for bracing the end structure adjacent the middle of the width of the car.

112. In a mine or similar rail car, the combination of side beams, car wheels and axles in supporting relation to the side beams, a transverse flanged metal end member connected to said side beams and having an upright wall, and a plate metal member providing at least a part of the lading bottom of the car and connected to the side beams at a low level thereof, said side beams and end member extending above and below the horizontal plane of the axes of the car wheels, said plate metal member including a portion extending beyond the said upright walls and beneath the end member and secured to the said end member.

113. In a mine or similar rail car, the combination of side beams, car wheels and axles in supporting relation to the side beams, a transverse flanged metal end member connected to said side beams and having an upright wall, and a plate metal member providing at least a part of the lading bottom of the car and connected to the side beams at a low level thereof, said side beams and end member extending above and below the horizontal plane of the axes of the car wheels, said plate metal member extending upward and outward in the direction of length of the car and including a portion extending beyond the said upright wall and above the end member and secured to the said end member.

114. In a self-clearing end-dump mine car for discharging all its lading at its forward end when the car is tilted forward for end-dumping, the combination of car wheels, car axles, side sills, a lading bottom structure supported by the side sills with at least portions of said bottom structure lying below the horizontal plane of the axes of the car wheels, a forward rigid end struc-

ture which includes a transverse bumping structure extending transversely of the lading body from side sill to side sill and projecting longitudinally of the car beyond the lading body thereof, and which end structure also at least in part is located above the said horizontal plane whereby at least part of the lading longitudinally rearward of portions of the said end closure wall lies below the tops of these portions, the car structure also providing deflector surfaces at the said forward end of the car whereby this said lading will be gradually deflected in respect of the said forward portions whereby it will be effectively discharged when the car is tilted forward for end-dumping and whereby no lading will pass underneath the said end closure wall structure.

115. In a self-clearing end-dump mine car for discharging all its lading through a single open space created by the relative movement of at least one gate at its forward end when the car is tilted forward for end-dumping, the combination of car wheels, a rear end closure wall to the lading body having a portion directly rearward of the rear car wheel extending below the top of said wheel, a lading bottom structure having a part of the said lading bottom surface which is located longitudinally rearward of the top of the said rear car wheel being substantially below the said top of the said rear wheel, upright side walls located outside the car wheels at the lateral edges of said part of the lading bottom surface, the lading body structure providing deflector surfaces extending to the upright side walls and having a substantially uniform forward and upward slope from said rearward part of the lading bottom surface to points over the said rear car wheel at an angle not exceeding 20° to the normal horizontal plane of the wheel axes, whereby that lading on the said lading bottom portions which is also substantially below the said top parts directly forward may be gradually deflected over the top parts whereby this lading may be readily discharged at the front end when the car is tilted forward for end-dumping.

116. In a low-floor mine or similar rail car for operating in trains with a lading body, car wheels and axles, the combination of a rigid traction truck frame for supporting the lading load without harmful end-drooping and for taking the haulage strains and bumping stresses, the said rigid frame being cut by the horizontal plane of the wheel axes and consisting of two

stiff flanged metal side sills and two stiff flanged metal transverse end sills perpendicular to the side sills and rigidly attached to the side sills substantially at their ends for forming a rigid metal frame which is rectangular in shape inside, a metal lading bottom structure extending longitudinally from end sill to end sill and extending transversely from side sill to side sill and being rigidly secured to the side and end sills for connecting and bracing the said rectangular frame for stiffness, the said lading bottom structure having at least substantial portions of its top surfaces lying below the horizontal plane of the axes of the car wheels, and a substantial transversely extending means located longitudinally beyond the said frame and beyond said end closure wall and in secured relationship with one of the said end sills for cushioning the said end sill against abrupt bumping shocks.

117. In a low-floor mine or similar rail car for operating in trains with a lading body, car wheels and axles, the combination of a rigid traction truck frame for supporting the lading load without harmful end-drooping and for taking the haulage strains and bumping stresses, the said rigid frame being cut by the horizontal plane of the wheel axes and consisting of two stiff flanged metal side sills and two stiff flanged metal transverse end sills perpendicular to the side sills and rigidly attached to the side sills substantially at their ends for forming a rigid metal frame which is rectangular in shape both outside and inside, a metal lading bottom structure extending longitudinally from end sill to end sill and extending transversely from side sill to side sill and being rigidly secured to the side and end sills for connecting and bracing the said rectangular frame for stiffness, the said lading bottom structure having at least substantial portions of its top surfaces lying below the horizontal plane of the axes of the car wheels, and a substantial transversely extending means located longitudinally beyond the said frame and beyond said end closure wall and in secured relationship with one of the said end sills for cushioning the said end sill against abrupt bumping shocks and for transferring the effects of such shocks laterally toward the ends of the side sills.

SANFORD INVESTMENT COMPANY,
Assignee of Audley Hart Stow, Deceased,
